SWITCHING SYSTEM

John Wicks, Oak Park, Ill., assignor to Associated Electric Laboratories, Inc., Chicago, Ill., a corporation of Delaware

Application July 28, 1938, Serial No. 221,722

38 Claims. (CL. 179—18)

The present invention relates to automatic switching systems and more particularly to switching systems of the character used in automatic telephone systems.

5 It is well known that connections between the lines of an automatic telephone system are established by routing the connections from the calling lines by way of automatically operating traffic concentration switches and one or more tandem connected impulse responsive numerical switches which are operative to select the desired lines and to establish connections thereto. Various types of automatic switches for performing the traffic concentration and line selecting 10 functions are known to the art. In applicant's prior Patent No. 2,137,517, granted Nov. 22, 1938, there is disclosed an improved form of switch which, because of its construction and mode of operation, is well adapted for use as a non-numerical switch or as an impulse responsive numerical switch. This improved switch, which falls broadly into the class known as cross bar switches, comprises a plurality of members or bars divided into two sets which may arbitrarily 15 be designated as comprising vertical bars and horizontal bars. Associated with each of the bars and adapted to be moved thereby are a plurality of sets of contacts. Actuating means comprising magnets individually associated with the operating bars are provided for moving the corresponding bars from one position to a second position. The bars of one of the two groups, such, for example, as the vertical bars, are so arranged relative to the bars in the other group, namely 20 the horizontal bars, that, when a selected one of the magnets associated with one of the horizontal and the magnet associated with a selected one of the vertical bars are energized, the contacts of a single set of contacts associated with the operated vertical bar are moved into engagement with the contacts of a single set of contacts associated with the operated horizontal bar. By 25 this arrangement, and when the contacts associated with the bars of one group are suitably multiplied, it is possible to select any desired line from a group of lines either incoming to or outgoing from the switch.

In any form of automatic telephone system, there must necessarily be provided, in addition 30 to the actual switching mechanisms per se, control apparatus for causing the switching mechanisms to be operated in the correct manner to carry out the desired line selecting and line switching functions. This control apparatus, in 35 its association with the respective numerical switches involved, is conventionally made responsive to impulses transmitted thereto from a calling subscriber's substation when the apparatus is taken for use. The arrangement of this control apparatus may take any one of various forms. 5 In order to simplify and economize in the matter of the apparatus provided in conjunction with each of the switches per se, there has been proposed in the past a form of system wherein separate communication and setting routes are utilized in setting up the switch trains by way of which established connections are routed. An improved form of this type of system is disclosed in applicant's prior Patent No. 2,081,027, granted 10 May 18, 1937. As described in this patent, the switches involved in the setting route are automatically released for further use immediately following their operation to cause the selection and operation of selected ones of the switches embodied in the communication channel. By 15 this arrangement, it is possible not only to simplify the actual construction of the switches which are tied up in the communication switch trains, but also greatly to reduce the number of switches required in the setting channel.

25 It is an object of the present invention to provide an improved automatic switching system of the type wherein separate setting and communication channels are utilized in setting up a communication connection and wherein the communication switches are of the cross bar type.

30 It is a further object of the invention to provide an improved arrangement of the character described wherein the conversational switches are positively controlled in a simple and reliable 35 manner through the setting or by-pass switches.

35 It is a still further object of the invention to provide an automatic telephone system of the character indicated wherein the by-pass or setting switches are arranged in an improved manner to enable the operating magnets of the cross bar conversational switches selectively to be energized in accordance with the line selecting digits of a directory number dialed at a calling substation embodied in the system.

40 The features of the invention as described in detail hereinafter are shown as being embodied in an automatic telephone system of the general character briefly described above, wherein separate communication and setting switches are utilized in setting up desired connections between the lines of the system and the communication 45 switches are of the exact form disclosed in applicant's above-noted co-pending application. In their broadest aspects, the objects as set forth 50 55

above are realized in accordance with the present invention by providing a system comprising a plurality of main or conversational switches of the cross bar type, a plurality of automatic bypass or setting switches, and apparatus comprising the by-pass switches for causing the main switches successively to operate to set up a connection therethrough. Each of the main switches includes two sets of operating magnets, the magnets of one set in each switch individually corresponding to groups of lines and the magnets of the other set individually corresponding to the lines of the groups. At each switching stage a selected magnet in each of the two sets of magnets embodied in the selected cross bar switch is caused to operate under the control of an operatively associated by-pass switch so that the desired connection is successively advanced to the desired line.

More particularly the system comprises, at each intermediate switching stage, a plurality of main switches of the cross bar type, each having access to a plurality of lines divided into groups and each including two sets of operating magnets. Associated with the main switches is a by-pass selector switch corresponding to each group of lines, one of which is arranged to be seized from the preceding switching stage. Each of the by-pass selector switches has associated therewith a tie switch having operating positions individually corresponding to the main switches and to the lines forming the group corresponding to the associated by-pass switch. Each of the by-pass selector switches includes control means operative in response to the seizure of the switch for causing the associated tie switch to operate to the position corresponding to a previously seized one of the main switches and, also, apparatus operative in response to the operation of the tie switch to the position just mentioned for causing the operation of the magnet in the seized main switch which corresponds to the group of lines corresponding to the seized by-pass switch. A line testing or line selecting switch is provided in each main switch which is arranged to respond to the operation of one of the group magnets in the same switch to select one of the lines of the group corresponding to the operated group magnet. Following the operation of the line testing switch of the seized main switch, means operative in response to the selection of one of the selected group of lines are caused to operate to energize the operating magnet of the seized main switch which corresponds to the selected line and to cause the operation of the tie switch, associated with the seized by-pass switch, to a position corresponding to the selected line.

Further features of the invention pertain to the particular arrangement of the apparatus whereby the above and additional improved operating features are attained.

The novel features believed to be characteristic of the invention are set forth with particularity in the appended claims. The invention, both as to its organization and method of operation, together with further objects and advantages thereof, will best be understood by reference to the specification taken in connection with the accompanying drawings, in which Figures 1 to 6, inclusive, illustrate the details of an automatic switch as disclosed in the above-mentioned co-pending application; Figs. 7 to 15, inclusive, illustrate an automatic telephone system having incorporated therein the features of

the present invention; and Fig. 16 illustrates the manner of assembling Figs. 7 to 15, inclusive, to form a unified system.

Referring now more particularly to Fig. 1 of the drawings, there is illustrated the mechanical arrangement of an automatic switch constructed and arranged in accordance with the invention disclosed and claimed in the above referred to co-pending application. As shown, the switch mechanism is adapted to be supported on shelves such, for example, as the shelves 13, 14, 15, 16 and 17 extending between and secured to side members 11 of a frame 12. Mounted on each of the enumerated shelves is a horizontal magnet, those for the shelves mentioned being indicated at 18, 19, 20, 21 and 22, respectively. Each of the horizontal magnets includes an armature upon which is mounted the horizontal member or bar for actuating the group of contact sets corresponding to the particular magnet. Thus, the magnets 18 to 22, inclusive, include, respectively, armatures 23, 24, 25, 26 and 27, upon which are mounted, respectively, the actuating bars 28, 29, 30, 31 and 32. Each of these bars is guided in its movement in the vertical plane by guide lugs mounted on the shelf carrying the associated magnet in a manner identical with that shown for the bar 28. The ends of the last-mentioned bar ride in slots provided in the upright portions of lugs 33 and 34, mounted at either end of the shelf 13. Each of the horizontal bars 28 to 32, inclusive, in cooperation with its respective associated horizontal magnet comprises means for actuating the contacts of an associated group of contact sets from their respective normal positions to their respective off-normal positions. Thus, the bar 28 has associated therewith a group of contact sets, four of which are indicated at 35, 36, 37 and 38. If the size of the switch requires that a large number of contact sets be placed under the control of each horizontal bar, two horizontal magnets may be required for actuating each bar, one magnet being positioned at each end of each bar. It will readily be apparent how such additional magnets could be embodied in the structure shown. It will further be apparent that the two magnets associated with each bar could have their respective windings connected in multiple for simultaneous energization.

Mounted on the lower shelf 17 is a group of vertical magnets, five of which are indicated at 39, 40, 41, 42 and 43, which individually include, in the order named, armatures 44, 45, 46, 47 and 48. Each of these armatures is arranged to actuate a vertical bar associated with one group of vertical contact sets and guided in its movement by a pair of brackets projecting outwardly from the shelves 13 and 16. These brackets, comprising the pair for guiding the bar associated with the magnet 39 in its movement, are shown at 64 and 65. The bars associated with the armatures noted are indicated at 49, 50, 51, 52 and 53, respectively, and each thereof carries a plurality of projecting arms individually associated with one of the contact sets of the corresponding group of vertical contact sets. Thus, the bar 49, which is under the control of the magnet 39, carries five arms, 54, 55, 56, 57 and 58, each of which projects inwardly and sidewise from the bar 49 so that, when the bar is pulled downwardly by the armature 44, all of the contacts included in the associated group of contact sets are moved from their respective normal positions to their respective off-normal

positions. The contact sets shown in association with the arms 54 to 58, inclusive, of the vertical bar 49 are indicated at 59, 60, 61, 62 and 63, respectively.

It will be understood that, when a switch of the above-described form, designed to have access to one hundred outgoing lines, is selectively operated to connect a line incoming thereto to any one of the outgoing lines, one hundred contact sets will be required in each of the plurality of groups of contact sets associated respectively with the horizontal and the vertical bars. This necessarily means that ten vertical bars will be required, each arranged to actuate a group of ten contact sets, and ten horizontal bars will be required, each similarly arranged to actuate a group of ten contact sets. It will further be apparent that the conductors of the incoming line including the trunk and test conductors thereof must necessarily be multiplied between the corresponding contacts of all of the contact sets of one plurality of groups of contact sets. Thus, if the incoming line is connected to the plurality of groups of contact sets associated with the horizontal bars, the conductors thereof must necessarily terminate at each of the contact sets actuated by each of these bars. The outgoing lines, on the other hand, terminate only at individual ones of the opposite contact sets or, in the assumed case, one line will terminate at each of the contact sets 59, 60, 61, 62, 63, etc., associated with the vertical bars.

Referring now more particularly to Fig. 2 of the drawings, there are illustrated the details of one of the horizontal magnets, such, for example, as the magnet 22 shown in Fig. 1, and of one of the spring assemblies associated with the corresponding horizontal bar 32 and the vertical bar 49. This magnet includes a magnetic core comprising a central leg 69 having a winding 70 wound thereon, a heel piece 71, a side piece 72, and an armature 27. The various contact spring assemblies, which individually comprise one contact of each of a pair of associated horizontal and vertical contact sets, are carried by an extension from the side piece 72. Thus, one of the assemblies in the pair of sets associated with the horizontal bar 32 and the vertical bar 49 comprises springs 74 and 75 mounted on the side piece 72 and insulated from each other by an insulating member 76, and from the assembly screws by additional insulating members 77 as shown. The armature 27 is pivoted at 79 and carries the cross bar 32 for actuating the group of springs including the contact set of which the spring 75 is a part. This cross bar is insulated from the spring 75 by an insulating member 80. Each of the other contact springs associated with each of the horizontal bars is similarly insulated from its associated bar. The upper associated set of contact springs comprising the set, of which the spring 74 forms a part, is under the control of the arm 53 projecting from the vertical bar 49. This arm is insulated from the associated set of contact springs by an insulating member 81. Each of the other contact springs associated with each vertical bar is similarly insulated from the corresponding bar.

Referring now to Fig. 3, there is illustrated the vertical magnet 39 for actuating the vertical bar 49 associated with the contact set including the contact spring 74. This magnet comprises a magnetic core having a central leg 84 having a winding 85 thereon, a heel piece 82, a side piece 83, and an armature 44. This armature is piv-

oted at 87 and is arranged to actuate its associated vertical bar 49 through a toggle member 88. As will be pointed out in greater detail hereinafter, the number of springs included in the assembly of each of the contact sets associated with the horizontal and vertical bars is dependent upon the particular arrangement of the control circuits for the switch. Obviously, the spring assemblies may be designed to suit the requirements of any particular application. If additional contact springs are required for the purpose of controlling the operation of the switch, such additional springs may be embodied in the magnet structure in any conventional manner.

In the operation of the switch as thus far described, and when one of the vertical magnets, such, for example, as the magnet 39, is selected and energized, the bar 49 carried by the armature 44 thereof is moved downward to actuate the contacts of all of the contact springs associated with this bar and included in the sets 59, 60, 61, 62 and 63, from their respective normal positions to their respective off-normal positions. This operation corresponds to the selection of a particular group of outgoing lines and, as will be pointed out in greater detail hereinafter, the particular vertical magnet which is subsequently energized corresponds to a particular line of the selected group. Following the energization of one of the vertical magnets, a selected one of the horizontal magnets, such, for example, as the magnet 22, is energized, thereby to actuate all of the contacts in the sets associated with the horizontal bar 32 from their respective normal positions to their respective off-normal positions and to complete a connection between the line incoming to the switch and a particular one of the lines in the selected group of lines outgoing from the switch. Thus, with the vertical magnet 39 and the horizontal magnet 22 energized, only the contacts included in the set of vertical contacts 63 will be in engagement with the contacts of the associated horizontal contact set, the remaining contact sets being disengaged due to the deenergized condition of the other vertical and horizontal magnets. Obviously, the selected horizontal magnet may be energized before the selected vertical magnet is energized and the same line selection will be achieved.

An understanding of the mode of operation of the switch is facilitated by considering the sequence of contact spring movements illustrated in Figs. 4, 5 and 6, for the spring assembly 74, 75, 76 associated with the horizontal magnet 22 and the vertical magnet 39. Normally, and with the two magnets noted deenergized, the springs 74, 75 and 76 are in the open contact positions illustrated in Fig. 4. With only the vertical magnet 39 energized, the spring 74 is pushed down so that the contacts on the springs 74 and 76 make contact, but the contacts between the springs 74 and 75 remain disengaged, as shown in Fig. 5. This permits the line testing operations to be performed. Thereafter, and when the horizontal magnet 22 is energized, the lower spring 75 is pushed up so that the contact of this spring engages the contact of the spring 74, as shown in Fig. 6. Thus, it will be seen that, with one horizontal magnet energized and one vertical magnet energized, the incoming line to the switch is connected only to a particular one of the outgoing lines. Obviously, the various line testing contacts may, if desired, be arranged to close in response to operation of the associated horizontal magnets providing the horizontal magnets are used as the

group select magnets and the vertical magnets are used to perform the line unit selecting operations.

Referring now more particularly to Figs. 7 to 15, inclusive, there is illustrated an improved 5 automatic telephone system of the by-pass type wherein automatic switches of the form just described are used as conversational switches to set up the desired connections between the various 10 lines. In general, the system comprises a plurality of telephones or subscribers' sub-stations, two of which are shown at A and B, adapted to be interconnected by means including their respective subscribers' lines 772 and 1599, and switch trains including four of the aforementioned 15 switches connected in tandem. These switch trains, when established, individually comprise a finder switch having access to the particular group of lines including the calling line, a first selector switch individually associated with 20 the finder switch delegated to the use of the calling line, a second selector switch accessible to the first selector switch and having access to a group of connector switches to which the called line extends, and finally a connector switch at 25 which the called line terminates. Thus, in the system shown, the line 772 terminates in the contact springs of a finder switch 100, which finder switch has individually associated therewith a first selector switch 200. The last-mentioned 30 switch, in turn, has access to groups of second selector switches, each second selector switch of each group having the contact springs associated with its vertical magnets multiplied to the corresponding contact springs of the other switches in 35 the same group and connected to trunk lines outgoing to the connector switches, one of which is indicated at 400. These connector switches are also arranged in groups, the corresponding contact springs associated with the vertical magnets 40 of the switches of each group being multiplied together and connected to the same subscribers' lines. Each of the lines extending to the various 45 finder and connector switches of the system has associated therewith a line circuit which conventionally comprises line and cut-off relays. Thus, the line 772 has associated therewith a line circuit which includes a line relay R700 and a cut-off relay R710.

As pointed out above, the various switches, 50 responding to and including the finder switch 100, the first selector switch 200, the second selector switch 300, and the connector switch 400, are not directly operable to perform the line selecting 55 functions, these switches being used only to set up the conversational circuits involved in the various connections. For the purpose of controlling the conversational switches, there are provided by-pass switches arranged in groups, which by-pass switches function to cause the conversational 60 switches to route a connection directly to a desired called line. Thus, there is associated with each group of one hundred lines a distributor switch, one of which is indicated at 150 associated with the group of lines terminating at the 65 finder switch 100. This distributor switch, which is of the rotary type, has access to a plurality of by-pass first selector switches, one of which is indicated at 250, which are arranged in groups and which, in combination with tie switches, one 70 of which is indicated at 125, cause the conversational finder switches, such as the switch 100, to operate to select a calling line and to extend this line to the trunk leading to the associated conversational first selector switch. Each of the by-pass 75 first selector switches further has access to a

number of groups of by-pass second selector switches, one of which is indicated generally at 350, which latter switches function, in combination with tie switches, one of which is indicated at 225, to cause a selected conversational first selector switch to select an idle conversational second selector switch. Each of the by-pass second selector switches also has access to certain groups of by-pass connector switches, one of which is indicated at 450, which latter switches, in combination with tie switches, one of which is indicated at 325, function to control the operation of the conversational second selector and connector switches. The by-pass selector and connector switches embodied in the system are preferably of the well-known two-motion Strowger type.

Each of the conversational finder switches has associated therewith a small test switch which is operative to select a calling line from a subgroup of ten lines previously selected through the operation of one of the horizontal magnets of the associated finder switch. Thus, there is provided in association with the finder switch 100 a test switch 175 which is operative to test the lines of 25 any selected subgroup of ten lines terminating at the switch 100. In a similar manner, each of the intermediate selector switches has associated therewith a small test switch for selecting an idle trunk from a group of trunks selected 30 through operation of one of the horizontal magnets embodied in the associated selector switch, the test switches associated with the intermediate conversational selector switches 200 and 300 being indicated at 275 and 375, respectively. 35 Each of the conversational connector switches has embodied therein a directing switch which is utilized in energizing selected ones of the horizontal and vertical magnets embodied in the associated crossbar switch, the directing switch for 40 the connector switch shown in Fig. 15 being indicated at 475. Each conversational connector switch further comprises switching and release relays, those embodied in the connector switch 400 being indicated at R1530 and R1520, respectively. 45

As pointed out above each of the conversational switches 100, 200, 300 and 400 and the other switches corresponding thereto is of the form illustrated in Fig. 1. The contact spring assemblies of the enumerated switches are slightly different from the spring arrangement shown in Figs. 1 to 6, inclusive, but the manner of altering the Fig. 1 arrangement to meet the operating requirements of the enumerated switches will be obvious to those skilled in the art. The line testing switches 175, 275 and 375, the directing switch 475, and the tie switches 125, 225 and 325 are all of the well known rotary type of which there are several well known commercial embodiments. Each of the rotary switches comprises a plurality 60 of sets of bank contacts, wipers respectively associated with the contact sets and means comprising an operating magnet and a ratchet and pawl mechanism for driving the wiper over the contacts of their respective associated contact sets. 65 The number of contact sets, the number of wipers and the number of contact points in the various switches varies in accordance with the requirements of each application. For example, the test switches 175, 275 and 375 each comprise two 70 sets of contacts of ten points each, and two wipers. On the other hand the tie switch 225 comprises twelve sets of contact sets numbered from 1287 to 1298 of one hundred points each, twelve wipers respectively associated with the contact 75

sets and numbered from 1228 to 1239, inclusive, and an operating magnet M1286. The tie switch 125 comprises eighteen contact sets of one hundred points each, eighteen wipers and an operating magnet M750. Finally, the tie switch 325 comprises fourteen contact sets of one hundred points each, fourteen wipers, and an operating magnet M1560.

As indicated above the conversational switches 10 require a minimum of control relay equipment, only the second selector switches having included therein any substantial amount of control apparatus. More particularly, the second selector switch 300 and the other similar switches have 15 individually associated therewith groups of relays arranged to perform the usual auxiliary functions incident to the completion of desired connections. The control equipment associated with the second selector switch 300 is illustrated in Fig. 12 and 20 comprises a line relay R1215 which is arranged to be held operated over a calling loop circuit extending to the switch 300, a battery reversing relay R1220 which is arranged to be held operated over the loop circuit extending to a called substation and a slow-to-release hold relay R1200. 25 For the purpose of returning busy tone to a calling party when a selected called line is found busy there is provided a slow-to-release busy relay R1210. The relay equipment also includes a 30 ringing and line switching relay R1260, a slow-acting ring cut-off relay R1250 and a slow-to-release booster battery control relay R1240 all arranged to operate in the manner set forth in detail hereinafter.

35 *Operation of the system generally*

Neglecting for the present the details of the 40 various control circuits and considering generally the operation of the system to set up a connection between two subscribers' lines, such, for example, as the lines 772 and 1599, on a call from the 45 substation A to the substation B, the operation of the apparatus is initiated when the subscriber at the telephone A lifts his receiver from its hook. Assuming that the various switches illustrated 50 are the switches utilized in setting up the connection, this operation on the part of the subscriber at the telephone A initiates the operation of the distributor switch 150 to select an idle by-pass first selector switch. Since it is assumed 55 that the switch 250 is the first switch available, this switch is seized, and certain relays included therein are caused to operate to initiate the operation of the tie switch 125. This tie switch 60 now functions to select the particular group of one hundred lines including the calling line by picking out the particular group of conversational 65 finder switches, including the switch 100, at which the lines of this group of one hundred lines terminate. Following the selection of this group of conversational finder switches, the tie switch 125 continues to operate to select an idle conversational 70 finder-selector link; as, for example, the link comprising the finder switch 100 and the selector switch 200, in the selected group. After this idle link is selected, the horizontal magnet HM120 associated with the group of ten lines including the calling line, is caused to operate 75 operatively to associate the ten lines with the test switch 175. The small rotary test switch 175 is next started into operation to select the particular calling line and to cause the operation of the vertical magnet VM130, which corresponds to the calling line, thereby to connect this line

through to the trunk line extending to the conversational selector switch 200. The calling line is also extended by way of certain of the contacts of the two contact sets 758 and 759, embodied in the tie switch 125, to the line conductors of the first by-path selector switch 250, whereby this selector switch is conditioned to respond to the impulses making up the first or thousands digit dialed at the calling subscriber's substation. When the calling line is switched through to the selector switch 250 the distributor 150 is released 10 for further use. In response to the impulses of the first digit, the wipers of the selector switch 250 are stepped to a position corresponding to the desired group of by-pass second selector switches, which second selector switches correspond to a particular group of one thousand lines and to a particular one of the horizontal magnets embodied in each of the conversational first selector switches. Following the selection of this 15 group of by-pass switches, the by-pass first selector switch 250 automatically operates to select an idle one of the by-pass second selector switches in the selected group and to seize the selected switch. Following this operation, the tie switch 225 is caused to operate to the position corresponding to the seized conversational selector switch 200. When the tie switch 225 is operated to this position the operation thereof is arrested and the horizontal magnet HM1270, corresponding 20 to the by-pass selector switch 350 and to the group of one thousand lines including the called line, is caused to operate, thereby operatively to associate the trunks of the group of ten conversational second selector switches corresponding 25 to HM1270 with the test switch 275. The test switch 275 is now started into operation to select an idle switch as, for example, the switch 300, in the selected group of conversational second selector switches. When the test switch 275 is 30 operated to the position corresponding to the idle switch 300, the operation of the test switch is arrested and the vertical magnet VM1280, corresponding to the switch 300, is caused to operate. Following the operation of VM1280, the tie switch 35 40 45 50 55 60 65 70 75 80 85 90 95 100 105 110 115 120 125 130 135 140 145 150 155 160 165 170 175 180 185 190 195 200 205 210 215 220 225 230 235 HM1500, corresponding to the group of one hundred lines including the called line, is energized and operates. Upon operating, the horizontal magnet HM1500 associates the trunks respectively extending to the conversational connector switches of the selected group with the test switch 375. Substantially simultaneously with the operation of HM1500, the test switch 375 is started into operation. When the wipers of this test switch are driven to a position corresponding to an idle switch of the selected group, such, for example, as the switch 400, the operation of the test switch 375 is arrested and the vertical magnet VM1510, corresponding to the selected connector switch 400 is caused to operate. Following the operation of VM1510 the tie switch 375 is operated to the position corresponding to the selected conversational connector switch 400.

During the interval when the sequence of operations described in the preceding paragraph are occurring the final two digits may be dialed at the calling substation. The by-pass connector switch 450 responds to the impulses of the final two digits by operating its wipers to the particular position corresponding to the called line 1599, and in so doing marks for subsequent operation the particular horizontal and vertical magnets of the selected conversational connector switch which correspond to the called line. The arrangement is such that the called line is tested to determine its idle or busy condition only following the operation of the selected by-pass connector switch to the position corresponding to the called line and the operation of the tie switch 325 to the position corresponding to the selected connector switch 400. If the called line is found busy, the line relay R1215, the busy relay R1210 and the hold relay R1200 are caused to operate and busy tone current is transmitted back over the calling loop circuit to the receiver at the calling subscriber's substation. If, on the other hand, the called line is idle, the line relay R1215, the hold relay R1200, the booster battery control relay R1240, and the switching relays R1260 and R1530 are caused to operate. Substantially simultaneously with the called line testing operations the directing switch 475 is started into operation. As the wipers of this switch traverse the contacts of their respective associated sets, the respective horizontal and vertical magnets HM1540 and VM1550, corresponding to the called line, are caused to operate. If the called line is idle, the two switching relays R1260 and R1530 are operated when the indicated horizontal and vertical magnets operate, so that ringing current is projected over the called line to energize the signal device provided at the called substation. The desired conversational connection is completed when the call is answered, at which time the ring cut-off relay R1250 and the battery reversing relay R1220 operate.

Following the operation of the magnets HM1540 and VM1550 the operated by-pass switches 350 and 450 are released for further use, the conversational switch train being held operated by virtue of the energized condition of the hold relay R1200. The release of the conversational switch train is primarily under the control of the calling party, although the battery reversing relay R1220, upon operating, functions to maintain the switches 300 and 400 operated independently of the hold relay R1200 so that these two switches are only released when the connection is cleared out at the called substation.

The control apparatus embodied in the by-pass switches

Referring now more particularly to the arrangement of the control relays and circuits included in the by-pass or control switches and considering first the link distributor switches, it is pointed out that the distributor switch 150, illustrated in Fig. 8 and common to one particular group of one hundred lines, comprises a ten-point rotary switch including thirteen sets of bank contacts, thirteen wipers and means comprising an operating magnet M830 and a ratchet and pawl mechanism, not shown, for driving the wipers over the contacts of their respective associated sets. The distributor switch further comprises a start relay R800 which is operative in response to the operation of any one of the line relays associated with the lines of the group corresponding to the switch 150, and a slow-to-release hold relay R820. Also embodied in the switch 150 is a fast-acting test relay R810 of the polarized type which is arranged to operate when the associated rotary switch is operated to a position corresponding to an idle by-pass first selector switch and functions to arrest the operation of the rotary switch and to cause the operation of the line and hold relays embodied in the selected by-pass switch.

The selector switch 250 comprises a Strowger switching mechanism including a vertical magnet M1040, a rotary magnet M1042, a release magnet M1041 and off-normal springs 1043, 1044, 1045, 1046, 1048, 1049 and 1050, all arranged to operate in the manner set forth in detail hereinafter. The relay equipment embodied in this selector switch comprises a line relay R1010, a slow-acting hold relay R1020, a slow-acting pulse circuit control relay R1030, and a fast-acting test relay R1000 of the polarized type which functions to terminate rotary movement of the Strowger switch wipers during a trunk hunting operation. The relay equipment further comprises the group of relays R900, R910, R920, R930, R940, R950 and R960, illustrated in Fig. 9, which are operative to control the operation of the tie switch 125 and of a selected conversational finder switch. More particularly, the shaded pole alternating current relay R950 is operative to condition the test relay R910 for operation when the tie switch 125 is operated to a position corresponding to a group of conversational finder switches having access to the calling line, the relay R910 is operative to arrest the operation of the tie switch 125 when it is operated to a position corresponding to an idle finder switch of the selected group, and the relay R900 is operative in response to operation of R910 to complete the operating circuit for the particular horizontal magnet of the selected finder switch which corresponds to the subgroup of ten lines including the called line. The relay R920 is operative to condition the relay R940 for operation when the relay R900 operates, and also to initiate the operation of the test switch, such, for example, as the switch 175, embodied in a selected conversational finder switch. The test relay R940 serves to arrest the operation of the test switch embodied in a selected finder switch when the test switch is operated to a position corresponding to the calling line and also to cause the operation of the particular vertical magnet in the finder switch which corresponds to the calling line. The relay R940 is also operative to cause the operation of R960, which latter relay functions as a test circuit

transfer relay. The slow-to-release relay R930 is provided for the purpose of conditioning the test relay R940 for operation and for holding the preceding distributor switch operated. The relay R930 also functions to prepare the operating circuit for a selected one of the vertical magnets of the selected finder switch. Alternating current energy for energizing the alternating current relay R950 is derived from an alternating current source, not shown, and is delivered to the relay R950 through a voltage stepdown transformer 970.

The by-pass second selector switch 350, illustrated in Figs. 11 and 13, is similar to the first selector switch 250 in that it includes a Strowger switching mechanism having embodied therein a vertical magnet M1370, a rotary magnet M1371, a release magnet M1373 and off-normal springs 1374, 1375, 1376, 1377, 1176, 1177 and 1178. The control equipment of this selector switch includes a line relay R1180, a slow-acting hold or release relay R1310, a pulse circuit control relay R1330 and a fast-acting trunk test relay R1300 of the polarized type. There is also provided a group of relays R1100, R1110, R1120, R1130, R1140, R1150 and R1160 which are arranged to control the operation of the tie switch 225 and the operation of a conversational first selector switch selected through operation of the tie switch 225. Of the enumerated relays, the shaded pole alternating current relay R1140 is arranged to operate to arrest the operation of the tie switch 225 when the tie switch is operated to a position corresponding to a selected one of the conversational first selector switches and also to cause the operation of the horizontal magnet in the selected conversational selector switch which corresponds to the by-pass switch 350. The relay R1140 is arranged to restore following the operation of the selected horizontal magnet in the selected conversational first selector switch. The two-step relay R1130 is arranged to respond to the operation and restoration of the relay R1140 by initiating the operation of the test switch associated with the selected conversational first selector switch. The two-step relay R1130, in cooperation with the slow-to-release relay R1110, also functions to condition the fast-acting polarized relay R1120 to operate when the test switch embodied in the selected conversational first selector switch is operated to a position corresponding to an idle conversational second selector switch in the selected group. As indicated, the relay R1120 is provided for the purpose of arresting the operation of the test switch in a selected conversational first selector switch and for the further purpose of energizing the particular vertical magnet of the selected conversational first selector switch which corresponds to the conversational second selector switch selected by the test switch embodied therein. In addition, the relay R1120 functions to initiate a second operation of the tie switch 225, the second operation being arrested when the tie switch is operated to the position corresponding to the selected conversational second selector switch through a second operation of the alternating current test relay R1140. Finally, the relay R1100 is arranged to respond to the second operation of R1140 and functions to maintain the partially completed conversational switch train operated and also to switch the calling loop circuit through to the control apparatus of the selector switch 350.

The arrangement of the control apparatus pro-

vided in each of the by-pass second selector switches is such that all line testing and certain of the other auxiliary control functions are performed therein rather than in the by-pass connector switches. More particularly, the control 5 of the tie switch associated with any selected by-pass connector switch is primarily achieved by operation of certain of the relays embodied in the by-pass second selector switches. Thus, there are provided in the by-pass selector switch 10 350 four relays R1150, R1340, R1350 and R1360 which are arranged to cooperate with certain of the relays provided in a by-pass connector switch selected by the switch 350, to control the operation of the tie switch associated with the selected by-pass connector switch and also the operation of the conversational second selector switch which is ultimately selected through the operation of the tie switch. The relay R1160, in cooperation with two additional relays R1170 and R1320, also functions to test the condition of a selected called line. More particularly, the relay R1120 is a busy 15 relay and is arranged to operate only when a selected called line is found to be in a busy condition. The relay R1170, on the other hand, is 20 an idle test relay and is arranged to operate only when a selected called line is found idle. 25

The by-pass connector switches, like the by-pass selector switches, are of the well-known Strowger type, that indicated at 450 being illustrated as comprising a Strowger switching mechanism, a vertical magnet M1424, a rotary magnet M1425, a release magnet M1409, and off-normal springs 1408 and 1415. The relay equipment in this connector switch comprises a start relay R1400 which is operative in response to the seizure of the switch by a preceding by-pass selector switch. This equipment further comprises a slow-to-release series relay R1420 arranged in a conventional manner and three relays R1410, 30 R1430 and R1440 which are arranged to cooperate with the previously mentioned group of relays embodied in the preceding second selector switch 350, or a similar switch, to control the operation of the tie switch 325 and the operation of a conversational second selector switch selected 35 through operation of this tie switch.

The Strowger switching mechanism embodied in the connector switch 450 is of somewhat special construction in that it is provided with a set of contacts 1465 which are arranged successively to be engaged by a wiper 1471 during the vertical movement of the wiper carriage structure embodied in the Strowger switching mechanism, and a second set of contacts 1466 which are arranged 50 successively to be engaged by a second wiper 1472 during rotary movement of the wiper carriage structure. The arrangement of the contacts in the two sets is such that the wiper 1471 engages a selected one of the contacts in the set 1465 irrespective of the rotary position ultimately attained by the wiper carriage structure during a line selecting operation. Only one of the contacts in the set 1466, on the other hand, is engaged by the wiper 1472 with this wiper standing 55 in any particularly rotary position, although the arrangement is such that the contacts of the set 1466 may be engaged by the wiper 1472 with the wiper carriage structure occupying any one of its vertical operating positions. The added 60 contact sets, together with the wipers respectively associated therewith, are arranged to cooperate with a small rotary marking switch 1460 for the purpose of selecting for energization the particular horizontal and vertical magnets of a selected 65 70 75

- conversational connector switch which correspond to a selected called line. This rotary marking switch comprises two sets of contacts 1461 and 1462, wipers 1463 and 1464 respectively associated with the two contact sets, and an operating magnet M1454 for driving the wipers over the contacts of their respective associated sets. The switch 450 further comprises two sets of off-normal springs 1456 and 1456', the springs of each set being arranged to be moved into engagement when the wipers of the switch 1460 are moved to their respective first off-normal positions. Energization of the magnet M1454 is under the control of a slow-to-operate relay 1450, which relay, in turn, is arranged to be energized only in response to the operation of a two-step relay R1450'. The relay R1450' also functions to complete the testing circuits by way of which a selected called line is tested to determine the idle or busy condition thereof. This relay is arranged to be energized in response to the operation and restoration of a slow-acting relay R1460' which is energized in parallel with the rotary magnet M1425 during the final series of impulses transmitted to the connector switch 450. For the purpose of maintaining the by-pass switch train operated during the interval when the marking switch 1460 is operating to cause the operation of the selected horizontal and vertical magnets of a selected conversational connector switch, the relay R1450' is arranged to maintain ground on the control conductor of the trunk incoming to the connector switch 450 for the duration of the indicated period. This ground is removed to permit the release of the by-pass switch train through the provision of a second two-step relay R1460' which is arranged partially to operate when the wipers of the switch 1460 are stepped one step off normal and completes its operation when the wipers of the switch 1460 have traversed all of their contacts and are returned to the home position thereof.

Operation of the apparatus to find a calling line

- Referring now in greater detail to the operation of the system to establish a connection between the substations A and B, and assuming that the apparatus illustrated is used in setting up the connection, operation of this apparatus is initiated when the calling party at the substation A removes his receiver from its hook to complete a circuit for energizing the line relay R700. This circuit extends from ground at RA712, by way of C714, the bridge placed across the line conductors C713 and C714 at the substation A, C713, RA711 and the winding of R700 to battery. The relay R700, upon operating, completes, at RA701, a path extending through the winding of the cut-off relay R710 for applying battery potential to the contact 723 of the switch 100, thereby to mark the calling line 772 in the subgroup of ten lines extending to the contact springs controlled by the horizontal magnet HMT20. At RA702, the relay R700 applies ground to the marking conductor C781, this conductor being common to the particular subgroup of ten lines which includes the calling line 772, and serving to identify the ten line subgroup which includes the calling line in the group of one hundred lines extending to the finder switch 100 when ground is applied thereto. From the above description, it will be apparent that the conductor C781 is multiplied to the contact springs corresponding to the springs associated with RA702 and respectively embodied in the ten line relays respectively associated with

the lines of one ten line subgroup. The remaining nine subgroups in a group of one hundred lines each has associated therewith an independent marking conductor, corresponding to C781, and terminating at the contact springs of the various line relays individually associated with the lines of the other subgroups. All of the marking conductors extend to contact springs of the start relay R800 embodied in the by-path distributor switch 150.

At RA703, the line relay R700 completes a circuit for energizing the start relay R800 in the by-path finder distributor switch 150, which switch, as was noted above, is common to the one hundred lines terminating at the finder switch 100. The circuit noted extends from ground at RA714, by way of R703, the start conductor C782 and the winding of R800 to battery.

The relay R800, upon operating, completes, at RA801, an obvious circuit for energizing the slow-to-release relay R820; prepares, at RA802, a circuit for energizing R950; and prepares, at RA803, a circuit, traced hereinafter, for energizing the horizontal magnet HMT20, associated with the subgroup of ten lines which includes the calling line 772. At RA804 and the remaining eight armatures of R800 circuits are prepared for energizing the other nine horizontal magnets of the switch 100. The relay R820, upon operating, completes, at RA821, an obvious circuit for energizing the lower winding of the polarized relay R810. This last-mentioned relay does not operate in response to the energization of its lower winding, it being so constructed that it operates only when both of its windings are energized, but, following its operation, is held operated so long as its lower winding is maintained energized. The energization of the lower winding of R810 does, however, render this relay exceedingly fast to operate when its upper winding is subsequently energized. At RA821, the relay R820 also completes a circuit for energizing M830, this circuit extending from ground at RA821 by way of RA813, the circuit-interrupting contacts associated with MA831, and the winding of M830 to battery. The magnet M830 now starts to operate, buzzer fashion, to drive the associated wipers 837 to 841, inclusive, to a position corresponding to an idle by-path first selector switch. The idle or busy condition of any by-path first selector switch, such, for example, as the by-path first selector switch 250, is determined by the nature of the potential existing on the control conductor embodied in the trunk line extending thereto. Thus, when the switch 250 is idle, battery is extended through the upper winding of R1030, the off-normal springs 1046, C975 and RA922 to the control conductor C848 extending to the switch 250 and terminated at a contact in the control contact set 833 of the finder switch 150. When, on the other hand, this by-path switch is busy, the control conductor C848 is either grounded or open-circuited. Assuming that the switch 250 is the first idle by-path first selector switch available, when the wipers 837 to 841, inclusive, are driven to the position corresponding to this switch, a circuit is completed for energizing the upper winding of R810 and the upper winding of the slow-to-release relay R1030 in series. This circuit extends from ground at RA821 by way of the upper winding of R810, C842, the wiper 838, C848, RA922, C975, the off-normal springs 1046, and the upper winding of R1030 to battery. The relay R810 operates immediately its upper winding is energized over the above-traced circuit and

interrupts, at RA813 and RC815, the above-traced operating circuit for M830, thereby to arrest the stepping operation of the wipers 837 to 841, inclusive. At RA813 and RC814, the relay R810 short-circuits its upper winding, thereby to render itself slightly slow to release. As indicated above, R810 is held operated so long as its lower winding is maintained energized. At RA812, the relay R810 opens a point in the operating circuit for R820 and, at RA811, it completes a circuit for energizing the line relay R1010, this latter circuit extending from ground by way of RA811, the switch wiper 837, C847, C973, RA1001, RC1002, and the upper winding of R1010 to battery. When the line relay R1010 operates, it completes, at RA1011 and RC1012, a circuit extending from ground at RA1009 for energizing the slow-to-release hold relay R1020, which latter relay operates to apply, at RA1021, ground potential to C975, thereby to complete obvious holding circuits for the relays R1030 and R810. Shortly following the operation of R1020, the relay R820 restores to open, at RA821, a point in the above-traced operating circuit for R810 and R1030. At RA1022, the relay R1020 completes an obvious circuit for energizing the lower winding of R1000. The last-named relay does not operate at this time, however, it being so constructed and arranged that it operates only when both of its windings are energized. The relay R1000 is rendered exceedingly fast to operate when its lower winding is energized, and is held operated, following its operation, so long as its lower winding is held energized. At RA1023, the hold relay prepares a test circuit, traced hereinafter, for energizing the upper winding of R1000. At RA1025, the hold relay prepares a circuit, traced hereinafter, for energizing the vertical magnet M1040 of the by-path selector switch 250 in accordance with the impulses making up the first digit dialed at the calling substation.

At RA1024, the relay R1020 completes a circuit for energizing the slow-to-release relay R930 and the upper winding of the polarized relay R940, this circuit extending from ground through RA1024 to C977 where it divides, one branch extending by way of RA947 and the winding of R930 to battery, and the other branch extending by way of the upper winding of R940 to battery. The relay R930 now operates to prepare, at RA933, a test circuit traced hereinafter for energizing the lower winding of R940. The relay R940 does not operate when its upper winding is energized over the circuit just traced, it being in this respect similar to each of the two relays R810 and R1000 in that it is rendered exceedingly fast to operate when its upper winding is energized but only operates when both of its windings are energized.

The hold relay R1020, upon operating, also completes a circuit for energizing the operating magnet M750 of the tie switch 125, this circuit extending from ground at RA1024 by way of C977, RA946, RA924, RA911, C783, the circuit-interrupting contacts associated with MA751 and the winding of M750 to battery. By virtue of the circuit-interrupting action of the contacts controlled by MA751, the magnet M750 now operates, buzzer fashion, to drive the wipers of the switch 125 over the contacts of their respective associated sets. The function of the switch 125 is two-fold. The first step in its operation is that of selecting the particular group of conversational finder switches at which are terminated the lines of the one-hundred-line group

including the calling line 712. Following this operation, the switch 125 is arranged to operate to select an idle one of the selected group of conversational finder switches. Any desired number of conversational finder switches may be included in each group. In the particular arrangement illustrated, and as will be brought out more in detail hereinafter, ten such switches are provided in association with the group of one hundred lines including the line 712. The testing means for determining when the group of conversational finder switches having access to the calling line is found by the tie switch 125, comprises the alternating current relay R950. Thus, when the wiper 762 is driven by the magnet M750 to a point where it engages the first of the contacts in the set 752 terminating the extra control conductor C784, a circuit is completed for energizing R950. This circuit extends from one terminal of the transformer secondary winding 971 by way of RA961, RC962, the winding of R950, RA923, C785, the wiper 762, C784, RA802, the wiper 839, C844, RA945, RC965 and RA964 to the opposite terminal of the transformer winding 971. When energized over the above-traced circuit, R950 operates, to prepare, at RA951, a circuit, traced hereinafter, for energizing the test relay R910. It will be observed that the nine contacts of the set 752 following that terminating C784 are multiplied together and to the contact terminating C784. Thus R950 is held operated during the continued operation of M750 further to advance the wipers of the tie switch 125. During continued operation of the tie switch 125 from the position corresponding to the first contact terminating C784, the conversational finder switches of the selected group are tested to determine the idle or busy condition thereof. Thus, if the switch 100 is idle, battery is extended by way of the resistor 737, the contact 736, and the armature 734 to the control conductor C779 of the link line 776. On the other hand, if this switch is busy, ground is present on the control conductor C779. So long as ground is found by the wiper 770 during the continued operation of the tie switch 125, no circuit is completed for energizing the test relay R910. When, however, an idle switch is found, a circuit is completed for energizing the test relay R910. Thus, assuming that the first switch 100 in the selected group is idle, the circuit for energizing R910 is completed immediately the wiper 770 is operated into engagement with the contact of the set 760 corresponding to this switch. This circuit extends from ground at RA951 by way of RA921, the lower winding of R910, C798, the wiper 770, C779, the armature 734, the contact 736, and through the resistor 737 to battery. When energized over the above-traced circuit, R910 first operates to complete, at the "X" contacts associated with RA913, a holding circuit for itself, this circuit extending from ground at RA1024 by way of C977, RA913 and the upper winding of R910 to battery. At RA911, the relay R910 interrupts the above-traced operating circuit for M750, thereby to arrest the operation of the tie switch 125 with the wipers thereof standing in the position corresponding to the selected switch 100. At RA914, the relay R910 applies ground to C798, which ground is extended by way of the switch wiper 770 to the control conductor C779 of the link line 776, thereby to mark the switch 100 as busy and to prevent seizure of the switch by another one of the by-path first selector switches. At RA912, the relay R910

completes a circuit for energizing R900, this circuit extending from ground at RA1024 by way of C977, RA946, RA912 and the winding of R900 to battery.

- 5 The relay R900, upon operating, completes a circuit for energizing the particular horizontal magnet which is associated with the ten line subgroup including the calling line 772. In this regard, it is emphasized that the line relay R700
 10 associated with the calling line 772, upon operating, prepares a circuit for energizing only the horizontal magnet of a selected conversational finder switch which corresponds to the ten line subgroup including the calling line. In the particular case under consideration HMT20 is energized, the circuit for this magnet extending from ground at RA714 by way of RA702, C781, RA803, the wiper 840, C845, RA901, C788, the wiper 764, C789, and the winding of HMT20 to
 15 battery. It will be apparent that, had the calling line been included in a different ten line subgroup, the line relay associated with this line would, upon operating, have prepared a circuit for energizing a different one of the horizontal magnets. As indicated previously, since each group of one hundred lines is divided into ten smaller subgroups of ten lines each, ten horizontal magnets are provided in each conversational finder switch and ten different conductors corresponding to and including C781, but respectively associated with different ten line subgroups, are provided. Also the rotary switch embodied in the by-path finder distributor switch
 20 150 includes a set of contacts for each of the subgroups, as does also the rotary switch embodied in the tie switch 125. In order to simplify the drawings, however, only two of the contact sets provided for this purpose are illustrated, namely, those for the horizontal magnets corresponding to and including HMT20, and those for the horizontal magnets of the group associated with the last ten line subgroup of the one hundred-line group.
 25 When the horizontal magnet HMT20 operates, it completes, at its armature 725, a holding circuit for itself, this circuit extending from ground, as extended over the above-traced path, to the control conductor C779, by way of the armature 725 and the winding of HMT20 to battery. The magnet HMT20 also operates all of its associated line switching contact springs corresponding to and including the springs 721, 722 and 723. Through this last-mentioned operation, the calling line is marked in the bank contacts of the rotary switch 175, the marking path extending from battery at the lower terminal of the cut-off relay R710 by way of the winding of R710, RA701, the contact springs 723 and 724 to the third contact of the set 743. Following the operation of HMT20, the switch 175 is started in operation to search for the particular calling line of the selected ten line subgroup. Thus, simultaneously with the completion of the operating circuit for HMT20 as traced above, there is completed a circuit for energizing R920, this latter circuit extending from ground at RA904, by way of RA926, and the lower winding of R920 to battery. The relay R920, upon operating, first completes, at RA925, a holding circuit for itself, this circuit extending from ground at RA1024 by way of C977, RA925 and the upper winding of RA920 to battery. At RA923, the relay R920 opens a point in the above-traced circuit for energizing R950, causing the last-mentioned relay to restore
 30 to open, at RA951, a point in the test circuit

 75

for energizing R910. At RA924, the hold relay R920 opens a further point in the operating circuit for M750. At RA926, the relay R920 opens a point in its operating circuit as traced above. At RA928, the relay R920 prepares a test circuit, 5 traced hereinafter, for energizing the lower winding of the test relay R940. At RA927, the relay R920 opens a further point in the test circuit, traced above and including the lower winding of R910. At RA921, the relay R920 completes a 10 circuit for energizing M740 embodied in the rotary switch 175, this circuit extending from ground by way of RA921, RA941, C794, the wiper 767, C795, the circuit interrupting contacts associated with MA741, and the winding of M740 to 15 battery. By virtue of the circuit interrupting action of the contacts associated with MA741, the magnet M740 operates buzzer fashion to drive the wipers 744 and 745 over the contacts of their respective associated sets 742 and 743. When 20 the wiper 745 is driven into engagement with the marked contact corresponding to the calling line 772, the above-mentioned test circuit is completed for energizing the lower winding of the test relay R940. In the present case, this circuit 25 extends from ground at RA928 by way of the lower winding of R940, RA933, C792, the switch wiper 766, C793, the wiper 745, the third contact of the set 743, the springs 724 and 723, RA701, and through the winding of R710 to 30 battery. When its lower winding is energized over the above-traced circuit, the relay R940 immediately operates to open, at RA941, a point in the above-traced operating circuit for M740, thereby to arrest the operation of the switch 175 35 with the wipers thereof standing in the position corresponding to the calling line 772. At RA943, the relay R940 completes a circuit for energizing the vertical magnet corresponding to the calling line, namely, the magnet VM730, this circuit 40 extending from ground at RA931 by way of RA943, C790, the switch wiper 765, C791, the switch wiper 744, the third contact of the set 742, and the winding of VM730 to battery. When 45 energized over the above-traced circuit, VM730 attracts its operating armature to actuate all of the switch springs associated therewith and in so doing moves the springs 731, 732 and 733 into engagement with the springs 721, 722 and 723, respectively. At its armature 734, the vertical magnet VM730 completes a holding circuit for 50 itself, which circuit extends from ground on the control conductor C779 by way of the armature 734, the contact 735 and the winding of VM730 to battery. It will be observed that, following the operation of VM730 and R940, the calling loop circuit is extended by way of the switch 100, the line 776, the tie switch 125, and the operated armatures RA942 and RA944 to the by-path selector switch 250 to hold the line relay R1010 55 operated independently of the relay R810 provided in the by-path finder distributor switch 150.
 When R940 operates, it functions to cause the release of the distributor switch 150. Thus, this relay, upon operating, opens, at RA946, a point 60 in the operating circuit for R900 and, at RA947, a point in the operating circuit for R930. At RA945, the relay R940 opens a further point in the test circuit, described previously, by way of which R950 was energized. At RA948, the relay 65 R940 completes an obvious circuit for energizing the lower winding of R960. Upon operating, the relay R960 completes a holding circuit for itself, this circuit extending from ground at RA1024 by way of C977, RA961 and the upper winding 70 75

of R960 to battery. At RA961 and RA964 and their respective associated contacts RC962 and RC965, the relay R960 opens two additional points in the test circuit over which R950 was energized. At RA961 and RA964 and their respective associated contacts RC963 and RC966, the relay R960 prepares a test circuit, traced hereinafter, for energizing the alternating current test relay R1140 or another relay corresponding to R1140 but embodied in a different by-path second selector.

When R900 restores, it opens a point in the above-traced circuit for energizing the horizontal magnet HM720 and a further point in the operating circuit for R920. When R930 restores, it interrupts, at RA931, a point in the above-traced operating circuit for VM730. At RA932, the relay R930 opens the holding circuit for R810, causing the last-named relay to restore. Before R930 falls back, however, the cut-off relay R710 associated with the calling line is caused to operate to open the operating circuit for R800. Thus, immediately VM730 operates, a circuit is completed for fully energizing the above-noted cut-off relay, this circuit extending from ground on the control conductor C719 by way of the switch springs 733 and 723, RA701 and through the winding of R710 to battery. The relay R710, upon operating, completes, at RA713, an obvious holding circuit for itself and opens, at RA714, a point in the above-described marking paths extending to the distributor. At RA713, the relay R710 also completes a path for applying ground to the control conductor C715 of the calling line 772, thereby to prevent the seizure of this line by one of the connector switches described hereinafter. At RA714, the relay R710 interrupts the above-traced operating circuit for the start relay R800. At RA712 and RA711, the relay R710 opens two points in the above-traced operating circuit for the line relay R700 and clears the calling line of the impedances of the windings of R700 which might interfere with the transmission of voice frequency and impulsing currents. Shortly following the restoration of R800 the relay R810 restores in the manner described above. When R810 restores, the distributor switch 150 is completely released and is in readiness for further use.

When the calling loop circuit is switched through to the selector switch 250 through the operation of R940 and VM730, dial tone current is returned over this loop to the calling subscriber to indicate that the dialing operation may be started. The path of this current extends from the ungrounded terminal of the dial tone source, not shown, by way of the dial tone lead 1048', the off-normal springs 1048 and 1049, RA1031, RA1032 of the operated relay R1030, the lower winding of R1010, RC1005, RA1004, C974, RA944, C797, the switch wiper 769, C778, the springs 732 and 722, C774, the receiver at the calling substation, C773, the springs 721 and 731, C777, the switch wiper 768, C796, RA942, C973, RA1001, RC1002, the upper winding of R1010, and the exchange battery back to the grounded terminal of the dial tone source. Following the switching through operation, the by-path selector switch 250 is conditioned to respond to the impulses making up the first digit dialed at the calling substation.

Operation of the apparatus in response to the impulses of the first digit

5 The vertical magnet M1040 responds to the

impulses making up the first digit dialed at the calling substation and functions to elevate the wipers 1055 to 1058, inclusive, of the Strowger switching mechanism embodied in the by-path selector switch 250 to a position opposite the desired level of bank contacts. More particularly, the line relay R1010, during each impulse of this digit, restores in response to the interruption of the loop circuit at the calling substation in the usual manner and, upon restoring, completes a circuit for energizing M1040. This circuit extends from ground at RA1009' by way of RA1011, RC1013, RA1025, RC1026, RA1034, and through the winding of M1040 to battery. During impulsing, the hold relay R1020 is held operated due to its slow-to-release characteristic. It will be observed that the lower winding of R1030 is energized in parallel with the winding of M1040 during the impulses of the first digit. Such energization is for the purpose of maintaining R1030 10 operated until the end of the digit. More particularly, when the enumerated wipers of the Strowger switching mechanism are stepped one step in the vertical direction, the off-normal springs 1046 are opened, to open the above-traced 15 operating circuit for R1030. Due to the continued periodic energization of the lower winding of this relay, however, and its slow-to-release characteristic, it stays operated until shortly following the end of the digit. The off-normal 20 springs 1043 and 1044 are also closed when the wipers 1055 to 1058, inclusive, are stepped the first step in a vertical direction, but closure of these springs is without effect at this time.

At the end of the first digit, R1010 is held 25 operated for a sufficient time interval to permit R1030 to restore. When R1030 falls back, it opens, at RA1031 and RA1032, a point in the above-traced path by way of which dial tone was conducted to the receiver at the calling substation. At RA1034, the relay R1030 opens a point in the above-traced circuit for energizing the winding of M1040 and its own lower winding in parallel. It will be noted that following the restoration of R1030, the line relay is held operated over a loop circuit which terminates at ground on RC1032' rather than at ground as extended to the dial tone lead 1048'. At RA1038, the relay R1030, upon restoring, completes a circuit for energizing the rotary magnet M1042, 35 this circuit extending from ground at RA1009' by way of RA1011, RC1012, C1068, the circuit interrupting contacts associated with the armature 1042', the off-normal springs 1043, RA1038 and through the winding of M1042 to battery. By 40 virtue of the circuit interrupting action of the springs associated with the armature 1042', the rotary magnet M1042 now functions to drive the wipers 1055 to 1058, inclusive, over the contacts of the selected level until an idle by-path second selector switch, in the group of switches having trunks terminated in the contacts of the selected level, is found. In this connection, it is pointed out that the idle condition of any one of the by-path second selector switches is indicated by the presence of battery potential on the control conductor of the trunk incoming thereto, whereas ground is present on the control conductor of the incoming trunk line if the switch is busy. For example, when the by-path second selector switch 350 is idle, battery potential is extended by way of the upper winding of R1330, the off-normal springs 1375, C1147 and RA1134 to the control conductor C1065 of the trunk incoming thereto. When, on the other hand, this 45

- switch is busy, ground at RA1313 is extended by way of C1147 and through RA1111 or RA1134 to the control conductor C1065. If it be assumed that the wipers 1055 to 1058, inclusive, are, during 5 their vertical motion, elevated to a position opposite the level of bank contacts terminating the trunk lines extending to the switches of the group including the switch 350 and that the switch 350 is the first idle switch available in the group, the 10 wipers noted will be rotated until they are moved into engagement with the contacts 1059 to 1062, inclusive. When this occurs, a circuit is completed for energizing the upper winding of R1000 in series with the upper winding of R1330, this 15 circuit extending from ground at RA1021 by way of the upper winding of R1000, RA1023, C1053, the switch wiper 1057, the contact 1061, C1065, RA1134, C1147, the off-normal springs 1375, and through the upper winding of R1330 to battery. 20 Obviously, had the trunk line including the control conductor 1065 been busy, the upper winding of R1000 would have been short-circuited so that the wipers 1055 to 1058, inclusive, would have continued to rotate. When, however, the above- 25 traced circuit is completed, R1000 immediately operates to open, at RA1009, the above-traced operating circuit for the rotary magnet M1042, thereby to arrest the movement of the switch wipers. The relay R1000, upon operating, completes, at RA1007, a multiple holding circuit for 30 itself, this circuit extending from ground on the control conductor C975 by way of RA1007 and the lower winding of R1000 to battery. At RA1008, the relay R1000 prepares a path for extending ground from C1147 to C975 when the line and hold relays in the switch 350 are caused to operate. At RA1008, the relay R1000 also completes a path for applying ground directly to the 35 control conductor C1065, thereby to mark the by-path second selector switch as busy. This path extends from ground at RA1021 by way of C975, RA1008, C1053, the switch wiper 1057 and the contact 1061 to the control conductor C1065. At RA1008, the relay R1000 prepares a further 40 point in the test circuit, traced hereinafter, for energizing the test relay R1140. At RA1009, the relay R1000 applies ground to C977, thereby to complete multiple holding circuits for R910, R929, R940 and R960. 45 At RA1001 and RA1004 and their respective associated contacts RC1003 and RC1006, the relay R1000 switches the calling loop circuit through to the selector switch 350, thereby to energize the line relay R1180. When R1180 operates, it completes, at RA1181 and RC1182, a circuit extending by way of C1157 for energizing the slow-to-release hold relay R1310. When R1310 operates RA1313, it applies ground to C1147, which ground is extended by way of RA1134, C1065, the 50 contact 1061, the wiper 1057, C1053 and RA1008 to the control conductor C975, thereby to hold the selector switch 250 operated independently of the line and hold relays R1010 and R1020, respectively. Immediately R1000 operates to switch the subscriber's loop circuit through to the selector switch 350, it opens, at RA1091 and RA1004 and their respective associated contacts RC1002 and RC1005, two points in the loop circuit over which the line relay R1010 is being held energized, 55 70 causing this latter relay to restore. When R1010 falls back, it opens, at RA1011 and RC1012, the operating circuit for R1020, causing this relay to restore. Due to its slow-to-release characteristic, the relay R1020 does not restore until after the operation of the hold relay R1310 embodied

in the by-path selector switch 350. Upon restoring, the relay R1020 opens, at RA1021 and RA1022, the multiple holding circuits for R1009, the latter relay being held energized over the circuit traced above and extending to ground at RA1313 of the operated hold relay R1310. At RA1023, the hold relay opens a point in the above-traced operating circuit for R1000. At RA1024, the relay opens the multiple path for applying ground to C977. At RA1025, the relay R1020 prepares a circuit, traced hereinafter, for energizing the release magnet M1041. Following the restoration of R1020, no further operations occur in the selector switch 250 until this switch is released.

Before describing the operation of the second by-path selector switch 350 and in order to complete the description of the operation of the first by-path selector switch 250, it is pointed out that in case all of the trunk lines terminated in a selected level of bank contacts of the switch 250 extend to busy second selector switches, busy tone will be returned over the loop to the calling subscriber to indicate that the call cannot immediately be completed. Thus, if all of the switches having trunk lines terminating in the contacts of the level including the contacts numbered from 1059 to 1062, inclusive, are busy, the rotary magnet M1042 operates to drive the wipers 1055 to 1058, inclusive, to the eleventh rotary off-normal position, at which time the off-normal springs 1048 and 1049 are opened, the off-normal springs 1049 and 1050 are closed, and the off-normal springs 1045 are closed. When the last-named off-normal springs are closed, a circuit is completed for again energizing R1030, this circuit extending from ground at RA1022 by way of the springs 1045 and the upper winding of R1030 to battery. Upon operating, the relay R1030 opens, at RA1038, a point in the above-traced operating circuit for the rotary magnet M1042, thereby to arrest the rotary movement of the wipers 1055 to 1058, inclusive. At RA1035, the relay R1030 opens a point in the circuit, traced hereinafter, for energizing the release magnet M1041. At RA1031 and 1032, the relay R1030 completes a path for conducting busy tone current by way of the subscriber's loop circuit to the receiver at the calling substation. This path is quite similar to that traced above for dial tone current, but extends from the busy tone source by way of the off-normal springs 1050 and 1049 rather than from the dial tone source by way of the springs 1048 and 1049. The calling subscriber, upon receiving busy tone, may initiate the release of the partially established switch train by hanging up his receiver. The manner in which the apparatus is released is described more in detail hereinafter.

Continuing now with the operation of the selected second by-path selector switch 350 and the tie switch 225 individually associated therewith, when the hold relay R1310 operates in response to the operation of the line relay R1180, it completes, at RA1312, an obvious circuit for energizing the lower winding of the polarized relay R1300, thereby to render R1300 fast to operate when its upper winding is subsequently energized. At RA1311 and RA1313, the relay R1310 prepares a test circuit, traced hereinafter, for energizing the upper winding of R1300. At RA1315 and RC1316, the relay R1310 prepares a circuit, traced hereinafter, for energizing the lower winding of R1330 during impulsing. At RA1314, the relay R1310 completes a circuit for energizing the low-

er winding of the polarized relay **R1120**, this circuit extending from ground by way of **RA1134**, **C1154** and the lower winding of **R1120** to battery. When ground is applied to **C1154**, the slow-to-release relay **R1160** is energized over a circuit extending by way of **RA1104**. Upon operating, the relay **R1160** opens, at **RA1161**, a point in the circuit, traced hereinafter, for energizing **R1210**. The application of ground to **C1154** also results in the energization of the slow-to-release relay **R1110** over a circuit extending by way of **RA1106**, **RC1107** and the winding of **R1110** to battery. The relay **R1110**, upon operating, prepares, at **RA1112**, a test circuit including the upper winding of **R1120**, the last-mentioned relay being of the polarized type, such that it only operates when both of its windings are energized, but is rendered fast to operate through the energization of its lower winding, and when once operated is held operated through the continued energization of its lower winding. The operation of the hold relay **R1310** also results in the completion of a circuit for energizing the operating magnet **M1286** embodied in the tie switch **225**, this circuit extending from ground by way of **RA1134**, **C1154**, **RA1142**, **RC1144**, **RA1138** and its associated lower contact, **C1113**, the circuit interrupting contacts associated with **MA1286**', and the winding of **M1286** to battery. Due to the circuit interrupting action of the contacts associated with **MA1286**', the magnet **M1286** now operates to drive the wipers of the tie switch **225** to the particular position corresponding to the conversational selector switch **200**. In this regard it is reiterated that the first conversational selector switch **200** is individually associated with the finder switch **100**, these two switches forming a finder selector link. Each of the horizontal magnets in the switch **200** corresponds to a different group of one thousand lines and to a particular first digit dialed at any calling substation. Hence, the by-path second selector switch **350** and the other switches of the same group correspond only to one horizontal magnet of each of the conversational first selector switches, this horizontal magnet in the case under consideration being the magnet **HM1270**. The switch **200** is identified in the banks of the tie switch **225**, individually associated with the by-path selector switch **350**, by the lead **C276**, corresponding leads being terminated in the contact set **1287** for each of the other conversational first selector switches accessible to the tie switch **225**. In between each pair of contacts of the set **1287** terminating any two of the several leads corresponding to and including **C276** are nine additional contacts, not shown, individually corresponding to nine of the ten trunks respectively associated with **HM1270** in the switch **200** or associated with the corresponding horizontal magnets of the other conversational first selector switches. In the case here being considered, when the wiper **1228** of the switch **225** is driven into engagement with the contact terminating **C276**, a circuit is completed for energizing the alternating current test relay **R1140**, this circuit extending from the right terminal of the transformer secondary winding **971** by way of **RA961**, **RC963**, **C799**, the switch wiper **771**, **C780**, the armature **1271**, **C276**, the contact of the set **1287** corresponding to the switch **200**, the wiper **1228**, **C1114**, **RC1133**, **RA1132**, the winding of **R1140**, **C1066**, the contact **1062**, the wiper **1058**, **C1054**, **RA1008**', **C976**, **RC966** and **RA964** to the opposite terminal of the winding **971**. When energized over the

above-traced circuit, the alternating current relay **R1140** operates to interrupt, at **RA1142** and **RC1144**, a point in the above-traced operating circuit for **M1286**, thereby to arrest the stepping operation of the tie switch **225**. The relay **R1140** also functions to complete a circuit for energizing the horizontal magnet corresponding to the first dialed digit and to the group of by-path second selector switches including the selected switch **350**, this circuit in the present case extending from ground at **RA1141** by way of **RA1131**, **C1118**, the wiper **1232**, **C280** and the winding of **HM1270** to battery. At **RA1142** and **RC1143**, the relay **R1140** completes a circuit for energizing the lower winding of **R1130**, this circuit extending from ground at **RA1134** by way of **C1154**, **RA1142**, **RC1143**, **RA1137**, and the lower winding of **R1130** to battery. The relay **R1130** is of the two-step type such that it only fully operates when its two windings are energized in series. When its lower winding is alone energized, **R1130** only closes the "X" contacts associated with **RA1135**, **RA1132** and **RA1138**. At the first-mentioned "X" contacts, the relay **R1130** completes an obvious path for short-circuiting its upper winding, thereby to prevent its full operation until **R1140** subsequently restores. At **RA1132** and **RC1133**, the relay **R1130** opens a point in the above-traced operating circuit for **R1140**. At **RA1138** and its associated lower contact, the relay **R1130** opens a further point in the above-traced operating circuit for **M1286**. The relay **R1140** restores after an interval and, in so doing, opens, at **RA1141**, the operating circuit for **HM1270** and, at **RA1142** and **RC1143**, a point in the path short-circuiting the upper winding of **R1130**. The relay **R1130** now completes its operation to prepare, at **RA1136**, a further point in the test circuit including the upper winding of **R1120** and, at **RA1137**, a point in the circuit, traced hereinafter, for energizing **R1100**. At **RA1134**, the relay **R1130** opens a point in the above-traced path for extending ground from **C1147** to the control conductor **C1065**, but, due to the energized condition of **R1110**, this path is now completed at **RA1111**. At **RA1131**, the relay **R1130**, upon operating, opens a further point in the above-traced operating circuit for the horizontal magnet **HM1270**. During the interval when **R1140** is operated, the magnet **HM1270** operates to complete, at its armature **1272**, a holding circuit for itself, this circuit extending from ground as applied to the control conductor **C179** by way of the armature **1272** and the winding of **HM1270** to battery. At its armature **1271**, the magnet **HM1270** opens a further point in the above-traced operating circuit for **R1140**. This magnet also attracts its operating armature, thereby to cause the associated horizontal bar to move the contact springs **1273** to **1276**, inclusive, to the off-normal position preparatory to extending the calling loop circuit to a selected one of the trunks outgoing from the switch **200**. Also, when **HM1270** operates it moves the spring **1275** into engagement with the spring **1274**', thereby to connect the control conductor **C283** of the trunk extending to the second selector switch **300** to the second contact of the test contact set **1278** embodied in the trunk hunting switch **275**. In a similar manner, the respective control conductors of the other nine outgoing trunks associated with **HM1270** are connected to the other nine contacts of the set **1278**. The test contacts of the contact set **1278** are multiplied to correspond to the contact springs of each of the ten horizontal magnets **75**

embodied in the switch 200, so that when any one of the horizontal magnets is energized, the control conductors of the ten trunks associated with the energized magnet are respectively connected to the ten test contacts of the contact set 1278.

The next operation to be performed is the selection of an idle one of the trunks in the group selected through the operation of HM1270. To this end and when R1130 operates, a circuit is completed for energizing M1287 embodied in the trunk hunting switch 275. This circuit extends from ground to RA1314 by way of C1154, RA1142, RC1144, and RA1138 and its associated upper contact, RA1123, RC1125, C1117, the wiper 1231, C279, the circuit interrupting contacts associated with MA1288, and through the winding of M1287 to battery. Due to the circuit-interrupting action of the contacts associated with MA1288, the magnet M1287 operates to drive the wipers 1285 and 1286 to a position corresponding to an idle one of the trunks in the selected group. The idle or busy condition of the trunks of the selected group is determined by the nature of the potential present on the contacts of the contact set 1278 respectively corresponding thereto. Thus, when the trunk terminating at the contact springs 1281 to 1284, inclusive, is idle, battery is impressed on the second contact of the set 1278 over a path including the resistor 291, RA1207', the control conductor C283 and the contact springs 1283, 1274' and 1275'. On the other hand, when this trunk is busy, ground is present on C283 and on the second contact of the set 1278. Assuming, for example, that the trunk terminating at the contact springs 1281 to 1284, inclusive, is the first available idle trunk of the selected group, when the wipers 1285 and 1286 are moved into engagement with their respective associated second contacts, the above-mentioned test circuit for energizing the upper winding of the test relay R1120 is completed, this circuit extending from ground at RA1136 by way of the upper winding of R1120, RA1112, C1116, the wiper 1230, C278, the wiper 1286, the contact springs 1275', 1274' and 1283, C283, RA1207' and the resistor 291 to battery. When its upper winding is energized over the above-traced circuit, the relay R1120 operates to open, at RA1123, a point in the above-traced operating circuit for M1287, thereby to arrest the operation of the switch 275. At RA1121, the relay R1120 completes a circuit for energizing the vertical magnet corresponding to the selected trunk or, in this case, VM1280. The circuit for energizing this magnet extends from ground at RA1121 by way of C1115, the wiper 1229, C277, the wiper 1285 and the winding of VM1280 to battery. When energized over this circuit VM1280 operates to complete, at its armature 1285', a holding circuit for itself, which holding circuit extends from ground as applied to the control conductor C779. The magnet VM1280 also attracts its operating armature to cause its associated vertical bar to move the contact springs 1281 to 1284, inclusive, into engagement with the springs 1273 to 1276, inclusive. Also, at the springs 1274' and 1283, the vertical magnet VM1280 opens a point in the above-traced testing circuit by way of which the upper winding of R1120 was energized. When VM1280 operates, a path is completed for marking the trunk terminating at the springs 1281 to 1284, inclusive, as busy, this path extending from ground

as applied to C779 by way of the springs 1275 and 1283 to the control conductor C283.

It will be apparent from the foregoing description that any one of ten trunks outgoing from the conversational selector switch 200 might have been selected through the trunk hunting operation of the switch 275. The tie switch 225 and its associated control equipment must, therefore, be capable of operating to the position corresponding to any one of the ten trunks associated with HM1270 in order to extend the subscriber's loop circuit to the control apparatus of the selector switch 350. In this regard, it is emphasized that the tie switch 225 is provided with ten points or operating positions for each of the switches, corresponding to and including the switch 200, to which it has access. In order to cause the tie switch 225 to operate to select the particular trunk previously selected by the trunk hunting switch 275, the relay R1120 is arranged to complete an alternative circuit for energizing M1286 embodied in the tie switch. This circuit extends from ground at RA1314 by way of C1154, RA1142, RC1144, RA1138 and its associated upper contact, RA1123, RC1124, RA1108, C1113, the circuit interrupting contacts associated with MA1286', and the winding of M1286 to battery. Through the circuit-interrupting action of the contacts associated with MA1286', the magnet M1286 now starts to drive the wipers of the switch 225 to the particular operating position corresponding to the selected trunk. For the purpose of determining this operating position, the conversation selector switch 200 is arranged so that, in its fully operated condition, it prepares a new test circuit for energizing the alternating current relay R1140. More particularly, when the wipers of the switch 225 are operated to a position corresponding to the selected trunk extending to the conversational second selector switch 300, this test circuit is completed. In the present case, the circuit extends from the right terminal of the transformer secondary winding 971 by way of RA961, RC963, C799, the switch wiper 771, C780, the contact springs 1276 and 1284, C284, the switch wiper 1236, C1128, RC1133', RA1132, the winding of R1140, C1066, the contact 1062, the wiper 1058, C1054, RA1008', C976, RC966 and RA964 to the opposite terminal of the winding 971. When energized over the above-traced circuit, the relay R1140 operates to open, at RA1142, a point in the above-traced alternative operating circuit for M1286, thereby to arrest the operation of the switch 225 with the wipers thereof standing in the particular operating position corresponding to the selected trunk. With the wipers of the tieswitch in this position, it will be observed that the subscriber's loop circuit is extended by way of the armatures RA1201 and RA1204, the conductors C281 and C282, the wipers 1233 and 1234, and the conductors C1119 and C1126 to the trunk line incoming to the selector switch 350.

Upon operating the second time, R1140 also completes, at RA1142 and RC1143 the above-mentioned circuit for energizing R1100, this circuit extending from ground at RA1314 by way of C1154, RA1142, RC1143, RA1137 and its associated upper contact, and the winding of R1100 to battery. When R1100 operates, it completes, at RA1105, a holding circuit for itself, which circuit extends from ground on C1154 by way of RA1106, RA1105 and the winding of RA1100 to battery. At RA1102 and RA1103, the calling subscriber's loop circuit is connected through to the trunk

conductor's **C1063** and **C1064**, thereby to hold the line relay **R1180** of the selector switch **350** operated independently of the condition of the preceding selector switch **250**. At **RA1101**, the relay **R1100** completes a path for applying ground to the control conductor **C283**, this path extending by way of **C1127** and the wiper **1235**. By virtue of the completion of this path, ground is maintained on the control conductor **C779** to hold the switches **100** and **200** operated independently of the condition of the selector switch **250**. At **RA1104**, the relay **R1100** opens a point in the operating circuit for the slow-to-release relay **R1160**, causing this latter relay to restore after an interval. At **RA1106** and **RC1107**, the relay **R1100** opens a point in the above-traced operating circuit for the slow-to-release relay **R1110**. When **R1110** restores, it opens, at **RA1112**, a point in the above-traced test circuit including the upper winding of **R1120** and, at **RA1111**, it disconnects the control conductor **C1147** from the control conductor **C1065**, thereby to initiate the release of the preceding by-path selector switch **250**.

25 Release of the by-path selector switch 250

When ground is removed from C1065, the hold-
ing circuit for R1000 is opened. Hence, the
restoration of R1110 is followed by the restoration
of R1000. Upon restoring, the relay R1000 opens,
at RA1008', a point in the above-traced alterna-
tive test circuit for energizing R1140, causing the
last-named relay to restore but without effect at
this time. At RA1009, the relay R1000, upon
restoring, removes ground from C971, thereby to
open a point in the common portion of the hold-
ing circuits for R910, R920, R940 and R960, caus-
ing all of these relays to restore. When these
four relays fall back, all of the control equipment
illustrated in Fig. 9 is restored to normal. It
will be noted that, when R940 restores, it opens,
at RA942 and RA944, two points in the loop cir-
cuit over which the line relay R1180 was held ener-
gized, this line relay now being held ener-
gized over the calling loop circuit as extended
through the operated selector switch 200.

50 When R1000 restores, it completes at RA1009', a circuit for energizing the release magnet M1041, this circuit extending from ground at RA1009' by way of RA1011, RC1013, RA1025, RC1027, RA1035, the off-normal springs 1044 and the winding of M1041 to battery. When energized over the above-traced circuit, M1041 operates to cause the wiper carriage structure of the 55 selector switch 250 to be restored to normal in the usual manner, at which time the off-normal springs 1043, 1044 and 1046 are returned to their respective normal positions. When the off-normal springs 1044 are opened, the above-traced 60 operating circuit for M1041 is interrupted to de-energize this magnet. Following the de-energization of M1041, the control apparatus embodied in the by-path selector switch 250 is entirely released and is in readiness for further 65 use.

Operation of the apparatus in response to the impulses of the second digit

As pointed out above, when the hold relay 70 R1310 operates, it completes, at RA1312, an obvious circuit for energizing the lower winding of the polarized relay R1306, whereby this latter relay is rendered exceedingly fast to operate when its upper winding is subsequently energized. At RA1311 and RA1313, the relay R1310

prepares a test circuit, traced hereinafter, for energizing the upper winding of R1300. At RAI313, the relay R1310 also completes a circuit for energizing the upper winding of R1330, this circuit extending from ground by way of RAI313, 5 the off-normal springs 1375 and the upper winding of R1330 to battery. The relay R1330, upon operating, prepares, at RAI331 and RAI332, a test circuit over which the busy relay R1320 may be energized. At RAI336, the relay R1330 opens 10 a point in the circuit, traced hereinafter, for energizing the rotary magnet M1371. Following the operation of R1330, the by-path selector switch 350 is conditioned to respond to the impulses making up the second digit dialed at the 15 calling substation.

The by-path connector switch grouping arrangement is such that each by-path connector switch is common to a particular group of five hundred lines. Following the operation of one of the first by-path selector switches, as, for example, the switch 250, the line selection is narrowed down so that the called line is identified as being in a particular group of one thousand lines. It remains, therefore, for the selected second by-path selector switch 350 to operate to select an idle by-path connector switch associated with the five hundred line group which includes the called line, and, second, the particular group of one hundred lines including the called line, of the selected five hundred line group. To this end, the first vertical row of contacts occupying the first five levels of the switch bank embodied in the switch 350 are arranged to terminate one trunk leading to a single by-path connector switch. This connector switch is associated with the first group of five hundred lines in the selected one thousand line group. The remaining nine vertical rows of contacts forming the remainder of the first five levels of the bank contact field similarly terminate trunks individually extending to connector switches associated with the first group of five hundred lines. In this connection it is pointed out that the conductors C1390 to C1399, inclusive, form a trunk extending to the connector switch 450, and these conductors may be terminated at any one of the ten vertical rows of contacts in the levels numbered from one to five, as, for example, the third row. The first vertical row of contacts in the contact levels numbered from six to zero, on the other hand, terminates a trunk leading to a connector switch commonly associated with the lines of the second five hundred-line group in the selected group of one thousand lines. Similarly, the remaining nine vertical rows in the levels numbered from six to zero individually terminate trunk lines extending to connector switches commonly associated with the second group of five hundred lines in the selected one thousand-line group. By virtue of this arrangement, it will be understood that, if the wipers 1378 to 1383, inclusive, of the Strowger switching mechanism embodied in the switch 350 are elevated to a position opposite the third level of bank contacts, for example,

set the third level of bank contacts, for example, and are then rotated to select a trunk leading to an idle by-path connector switch, this connector switch will be commonly associated with the lines of the first five hundred-line group. On the other hand, if these wipers are elevated to a position opposite the eighth level of bank contacts, for example, and are then rotated to select an idle trunk, the selected trunk will extend to a by-path connector switch commonly associated 70
75

with the second group of five hundred lines in the one thousand-line group.

Each of the by-path connector switches, as, for example, the switch 450, is operative to cause the operation of a selected horizontal magnet and a selected vertical magnet in any one of five different conversational connector switches for the reasons pointed out above, namely, that each by-path connector switch is commonly associated with a group of five hundred lines, whereas each conversational connector switch terminates only one hundred lines. It follows, therefore, that the selection of a particular idle conversational connector switch having access to the group of one hundred lines including the called line evolves upon the selected second by-path selector switch. To this end, the arrangement is such that each level of bank contacts in each second by-path selector switch corresponds to a particular group of one hundred lines so that, when any one of these switches is caused to operate to select an idle connector switch, it conditions the selected switch to control only a conversational connector switch having access to the particular group of one hundred lines which includes the called line. More particularly, the first level of bank contacts in the switch 350 corresponds to the first group of one hundred lines in the first larger group of five hundred lines of the selected one thousand line group; the second level of bank contacts corresponds to the second group of one hundred lines; the third level of bank contacts corresponds to the third group of one hundred lines, all in the first five hundred line group, and so on. With the foregoing brief description in mind, it is believed that the line and switch grouping arrangement will be clearly apparent from the following description of the operation of the selector switch 350 to select an idle one of the by-path connector switches associated with the group of five hundred lines including the called line and to condition the selected switch to select and control a conversational connector switch terminating the called line.

The switch 350 responds to the impulses of the second digit to perform its particular switch selecting operations. Thus, at the beginning of the first impulse of the second digit dialed at the calling substation, the calling loop circuit is opened to cause the restoration of the line relay R1180. This line relay, upon restoring, completes a circuit for energizing the vertical magnet M1370, which circuit extends from ground at RAI181 by way of RC1183, C1158, RAI315, RC1316, C1156, RAI173, C1155, RAI305, RC1307 and the winding of M1370 to battery. The vertical magnet now operates to step the wipers 1378 to 1383, inclusive, to a position opposite the first level of bank contacts. Simultaneously with this stepping operation, the off-normal springs 1375 are opened to interrupt the above-traced operating circuit for R1330. Due to the slow-to-release characteristic of this relay, however, it remains operated through its repeated energization during the impulses of the second digit over a circuit extending from ground at RAI181 by way of RC1183, C1158, RAI315, RC1316 and the lower winding of R1330 to battery. The off-normal springs 1376 and 1377 are also closed when the wipers of the switch 350 are stepped to the first vertical off-normal position, but without effect at this time. The vertical magnet M1370 is energized and deenergized once for each impulse of the second digit dialed at the calling sub-

station, and through its operation, the wipers 1378 to 1383, inclusive, are stepped vertically to a position opposite the level of bank contacts corresponding to the number of impulses making up this digit. If, for example, the called line 1599 is in the fourth one hundred-line group of the first larger group of five hundred lines of the selected group of one thousand lines, the second digit dialed at the calling substation will necessarily comprise four impulses so that, at the conclusion of the digit the wipers of the switch 350 will be standing in a position opposite the fourth level of bank contacts. Similarly, if the called line is included in the second group of one hundred lines of the first larger group of five hundred lines, the second digit will necessarily comprise only two impulses. On the other hand, if the called line is in the third group of one hundred lines forming a part of the second larger group of five hundred lines, the second digit must necessarily comprise eight impulses so that, at the conclusion of the digit, the wipers will be standing in a position opposite the eighth level of bank contacts. Since, in the present case, the switch 450 is commonly associated with the first group of five hundred lines in the selected one thousand-line group, it will be assumed that the called line is included in the third one hundred-line group forming a part of this first five hundred-line group. The second digit will, therefore, comprise three impulses so that, at the conclusion thereof, the wipers will be left standing in a position opposite the third level of bank contacts. Shortly following the end of the second digit, R1330 restores to complete a circuit for energizing the rotary magnet M1371, this circuit extending from ground at RAI181 by way of RC1182, C1157, RAI308, the circuit-interrupting contacts associated with MA1372, the off-normal springs 1371, RAI336 and the winding of M1371 to battery. Due to the circuit-interrupting action of the springs controlled by MA1372, the magnet M1371 is repeatedly energized to drive the wipers 1378 to 1383, inclusive, across the contacts of the selected contact level. The rotary movement of the wipers is continued until such time as they are stepped into engagement with a contact set terminating a trunk leading to an idle one of the connector switches in the selected group. In this regard, it is pointed out that the idle or busy condition of the connector switches depends upon whether ground or battery potential is present on the control conductors embodied in the trunks individually extending thereto. For example, if the switch 450 is busy, ground is present on the control conductor C1390 thereof and is extended by way of this conductor to each of the five contacts forming the contact group 1384 whereas, if this switch is idle, battery potential is extended to C1390 through the resistor 1407 and RAI401. Assuming that the connector switch 450 is the first idle switch in the selected group, when the wipers 1378 to 1383, inclusive, are driven into engagement with the contacts terminating the trunk extending to this switch, the above-mentioned test circuit is completed for energizing the upper winding of the polarized relay R1300, this circuit extending from ground at RAI313 by way of C1147, the upper winding of R1300, RAI311, the switch wiper 1378, the third contact of the group 1384, C1390, RAI401 and the resistor 1407 to battery. Obviously, when the wiper 1378 encounters grounded contacts corresponding to busy connector switches during the rotary movement of 75

the switch wipers, the upper winding of R1300 is short-circuited. The relay R1300 immediately operates, when its upper winding is energized over the above-traced circuit, and interrupts at 5 RA1308, a point in the above-traced operating circuit for M1371, thereby to prevent further rotary movement of the switch wipers. At RA1301 and RA1302, the relay R1300 completes an obvious path for short-circuiting its upper winding, 10 thereby to render itself slightly slow-to-release. At these same armatures, a path is completed for applying ground to C1390, thereby to mark the connector switch 450 as busy and to cause the operation of R1400 embodied in the seized connector switch 450. More particularly, the circuit 15 for energizing R1400 extends from ground at RA1312 by way of RA1302, RA1301, the switch wiper 1378, the third contact of the group of contacts 1384, C1390 and the winding of R1400 to battery. The resulting operation of R1400 initiates the operation of the tie switch 325 associated with the connector switch 450 to select the second conversational selector switch 300 and to cause the energization of the proper horizontal magnet embodied therein. At RA1309 and RA1309', the relay R1300 prepares circuits, traced hereinafter, which are utilized in controlling the operation of the tie switch 325 to select the second conversational selector switch 300 already selected by the tie switch 325. At RA1304, the 20 relay R1300 applies multiple ground to C1154 to provide multiple holding circuits for R1100, R1120 and R1130. At RA1308', the relay R1300 opens a point in the circuit, traced hereinafter, for energizing the release magnet M1373. At RA1303, the relay R1300 completes an alternative circuit for energizing R1330, this circuit extending from ground at RA1304 or RA1314 by way of C1154, RA1362', RC1364, RA1303 and the upper winding of R1330 to battery. The relay R1330 is held operated over this circuit to hold prepared the line test circuit for energizing R1320 until the relay R1360 is caused to operate.

The arrangement of the apparatus is such that the stepping magnets embodied in any selected bypass connector switch are controlled by the impulsive or line relay provided in the preceding operated second bypass selector switch. More particularly, when R1300, embodied in the switch 350 operates, it prepares, at RA1305 and RC1306, a circuit, traced hereinafter, for energizing the vertical magnet M1424 in accordance with the impulses of the third digit dialed at the calling substation and for energizing the rotary magnet M1425 in accordance with the impulses of the fourth digit dialed at the calling substation. Following the operation of R1300 and R1400, the tie switch 325 is started in operation to find the conversational selector switch 300 previously selected by the trunk hunting switch 275 and the tie switch 225. Before describing the operation of the tie switch 325, however, it is pointed out that, in the event all of the connector switches in the selected group are busy at the time the trunk hunting operation of the switch 350 is initiated, the last-named switch will operate to return busy tone over the loop to the calling subscriber's substation to indicate that the connection cannot immediately be established. More particularly, under these conditions, the wipers 1378 and 1383, inclusive, are driven by the rotary magnet M1371 to the eleventh rotary off-normal position, at which time the off-normal springs 1374 are closed, the off-normal springs 1176 and 1177 are opened, and the off-normal springs 1175 and 1178 are closed. When the springs 1374 are

moved into engagement, an alternative circuit is completed for energizing the upper winding of R1330, this circuit extending from ground at RA1312 by way of the springs 1374 and the upper winding noted to battery. The relay R1130, 5 upon operating, opens, at RA1336, a point in the previously traced operating circuit for M1371, thereby to arrest the rotary movement of the wipers 1378 and 1383, inclusive. When the springs 1177 and 1178 are closed, busy tone current is conducted by way thereof, the lower winding of R1180, and the subscriber's loop to the receiver at the calling substation, thereby to signal the calling party that the desired connection cannot be obtained. The line relay R1180 10 is held operated during the busy signaling by virtue of the presence of ground on the off-normal spring 1172, this ground being extended to the spring noted through the busy tone source. Following the operation of R1330, no further operation of the switching apparatus occurs. The calling party, upon receiving busy tone, may 15 initiate the release of the connection by hanging up to cause the restoration of the line relay R1180. When R1180 restores, it opens the operating circuit for the hold relay R1310, which latter relay, upon restoring, opens directly or causes the holding circuits for all of the operated relays and magnets in the partially completed switch train, thus causing the connection to be 20 cleared out. The manner in which the operated selector switch 350 releases is described more in detail hereinafter.

Continuing now with the operation of the apparatus to extend a connection to the called line 35 1589, when the relay R1400 operates, it opens at RA1401, a point in the path for applying battery to C1390. At RA1402 and RC1403, the relay R1400 completes an obvious circuit for energizing the lower winding of the polarized relay 40 R1440, thereby to render the last-mentioned relay fast to operate when its upper winding is subsequently energized. At RA1405, the relay R1400 completes a circuit for energizing the operating magnet M1560 embodied in the tie switch 45 M325, this circuit extending from ground at RA1151 by way of RC1153, C1163, RA1309, RA1367 and its associated lower contact, the wiper 1382, the third contact of the group 1388, C1392, RA1438, RC1439, RA1411, RC1413, 50 RA1405, C1426, the circuit interrupting contacts associated with MA1561 and the winding of M1560 to battery. Due to the circuit-interrupting action of the contacts associated with MA1561, the above-traced circuit is repeatedly 55 interrupted so that M1560 is alternately energized and deenergized to drive the wipers of the switch 325 to a position corresponding to the conversational second selector switch 300. This position is determined by the testing circuit including the extra control conductor C287 of the trunk incoming to the selected conversational second selector switch 300. More particularly, when the wipers of the switch 325 are driven to a position such that the wiper 1578 engages the 60 contact terminating C1590, a circuit is completed for energizing the alternating current test relay R1150, this circuit extending from the upper terminal of the transformer secondary winding 1167 by way of the winding of R1150, C1146, the 65 wiper 1239, C287, the armature 1501, C1590, the wiper 1578, C1489, RC1432, RA1431, C1399, the third contact of the contact group 1389, the wiper 1383, RA1369, RA1309, C1164 and RA1175 to the opposite terminal of the winding 1167. 70 75

When energized over the above-traced circuit, R1150 operates to open, at RA1151 and RC1152 a point in the above-traced operating circuit for M1560, thereby to arrest the operation of the tie switch 325 with its wipers standing in the position corresponding to the conversational second selector switch 300. At RA1151 and RC1152, the relay R1150, upon operating, completes a circuit for energizing the slow-to-release relay R1340, this circuit extending from ground at RA1151 by way of RC1152, C1159, RA1366 and the winding of R1340 to battery. The relay R1340 also completes, at RA1342, a circuit extending by way of RA1352 and RC1354 for energizing the lower winding of R1350. The last-named relay now partially operates to complete, at the "X" contacts associated with RA1351, a path for short-circuiting its upper winding, this path extending from ground at RA1314 or RA1304 by way of C1154, RA1351, the upper winding of R1350, RC1354, and RA1352 back to ground at RA1342. The relay R1350 is of the two-step type, such that it only partially operates when its lower winding is alone energized and assumes its fully operated position only when its two windings are energized in series.

At RA1343 the relay R1340 completes a circuit for energizing the upper winding of R1430, this circuit extending from ground by way of RA1343, RA1365, the wiper 1381, the third contact of the group 1387, C1391, RA1447, RA1434, RC1435 and the upper winding of R1430 to battery. When its upper winding is energized, the relay R1430 partially operates to complete at the "X" contacts associated with RA1437 a path for short-circuiting its lower winding which path includes a portion of the circuit just traced and extends back to ground at RA1402. At the "X" contacts associated with RA1438, the relay R1430 prepares an alternative circuit, traced hereinafter for energizing M1560. At RA1438 and RC1439, the relay R1430 opens a further point in the original operating circuit for M1560. The relay R1430, which is also of the two-step type does not complete its operation until its two windings are energized in series.

At RA1341, the relay R1340, upon operating, completes a circuit for energizing the particular horizontal magnet of the switch 300, which corresponds to the group of one hundred lines including the called line 1599. In this regard it is pointed out that each of the horizontal magnets embodied in the conversational second selector switch 300 corresponds to a different group of one hundred lines forming a part of the selected one thousand line group. Hence, through the selective energization of these magnets, it is possible to select the group of conversational connector switches made up of the switches having access to the called line. More particularly, when the tie switch 325 is operated to the position corresponding to the crossbar selector switch 300, circuits are prepared by way of the conductors C1591 to C1595, inclusive, for energizing any one of five horizontal magnets embodied in the selector switch 300. These circuits are, however, dependent for their completion upon the particular position occupied by the wipers of the operated bypass second selector switch 350, so that the position of the last-named switch determines which of the five different horizontal magnets will ultimately be energized. Thus, with the wipers 1378 to 1383, inclusive, occupying a position in the third level of bank contacts and standing in engagement with the set of contacts ter-

minating the trunk extending to the switch 450, the horizontal magnet HM1500 is energized in response to the operation of R1340. Specifically, the circuit for energizing this horizontal magnet extends from ground at RA1341 by way of RC1362, RA1361, the wiper 1379, the third contact of the contact group 1385, C1383, RA1444 and its associated upper contact, C1492, the switch wiper 1581, C1593 and the winding of HM1500 to battery. Obviously, had the wipers of the selector switch 300 been operated to a position corresponding to the fourth one hundred-line group forming a part of the larger first five hundred-line group of the selected one thousand lines, a different horizontal magnet in the switch 300 would have been energized, namely, that corresponding to the fourth contact of the contact group 1385. When energized over the above-traced circuit, the magnet HM1500 operates to complete, at its armature 1502, a holding circuit for itself, this circuit extending from ground as applied to the control conductor C283 by way of RC1267, RA1265, C290, the armature 1502 and the winding of HM1500 to battery. At its armature 1501, the magnet HM1500 opens a point in the above-traced test circuit including the winding of R1150. The magnet HM1500 further functions to move its associated horizontal actuating member to the off-normal position, thereby to cause the springs 1503 to 1506, inclusive, and the other springs controlled thereby to be moved to a position to be engaged by the respective associated contacts controlled by a selected one of the vertical magnets.

When R1150 restores following the operation of HM1500, it reprepares the operating circuit for M1560 and opens, at RA1151 and RC1152, a point in the above-traced operating circuit for R1340, causing the last-named relay to restore after an interval to open, at RA1342, a point in the above-traced path for short-circuiting the upper winding of R1350. At RA1343, the relay R1340 opens a point in the above-traced path short-circuiting the lower winding of R1430. The two relays R1350 and R1430 now assume their respective fully operated positions. At RA1434 and RC1435, the relay R1430 opens a further point in the path, traced previously, for short-circuiting its lower winding. At RA1434 and RC1436, the relay R1430 prepares a circuit traced hereinafter for energizing M1509. At RA1434 and RC1433, the relay R1430 prepares an alternative test circuit for again energizing the alternating current test relay R1150. At RA1436, the relay R1430 prepares a test circuit, traced hereinafter, for energizing the upper winding of the polarized relay R1440 when the trunk hunting switch 375 is operated to a position corresponding to an idle trunk of the selected trunk group. When the relay R1350 fully operates it opens, at RA1352 and RC1354, a further point in the path for short-circuiting its upper winding and prepares at RA1352 and RC1353 a circuit for energizing R1360. At RA1355, the relay R1350 completes a circuit for energizing M1509, this circuit extending from ground by way of RA1355, RA1365, the wiper 1381, the third contact of the group 1387, C1391, RA1441, RA1434, RC1436, C1429, the wiper 1576, C1588, the circuit-interrupting contacts associated with the armature 1519 and the winding of M1509 to battery. Due to the circuit-interrupting action of the contacts associated with the armature 1519, the magnet M1509 starts operating, buzzer fashion, to drive the wipers of the switch 375 to a

position corresponding to an idle trunk in the selected group of trunks.

From the immediately preceding description, it will be apparent that, when HM1500 operates, the switch 300 is only capable of connecting the trunk incoming thereto to one of a group of ten trunks individually extending to the conversational connector switches having access to the called line. The selection and energization of HM1500 is tantamount to the selection of the particular group of one hundred lines which includes the desired called line since the group of conversational connector switches through which the connection may be routed is determined when this horizontal magnet operates. Logically, the next operation to be performed is the selection of an idle conversational connector switch in the selected group. To this end the horizontal magnet HM1500 is arranged so that when it operates it connects the private or control conductors of the trunks leading to the respective conversational connector switches of the selected group to the ten contacts of the set 1508 embodied in the rotary switch 375. Thus, when the horizontal magnet noted operates, the control conductor of the trunk leading to the connector switch 400 is extended by way of the springs 1513, 1509', 1508', and 1507' to the third contact of the contact set 1508. Similarly, the private conductors of the remaining nine trunks in the group associated with HM1500 are individually connected through springs corresponding to those enumerated and controlled by HM1500 and the respective vertical magnets of the switch 300 to the other nine contacts of the contact set 1508. The condition of the conversational connector switches in the selected group is indicated by the nature of the potential appearing on the control or private conductors of the trunk lines individually extending thereto. For example, when the conversational connector switch 400 is idle, battery potential is extended by way of the resistor 1537, RC1536, and RA1534 to the control conductor of the trunk line incoming thereto. On the other hand when this switch is busy, ground potential is impressed upon the control conductor noted in a manner pointed out in detail hereinafter.

When the rotary switch 375 is started in operation in the manner described previously, it functions successively to test the trunks extending to the connector switches of the selected group. Assuming that the first two switches of this group are busy and that the third switch of this group, namely, the switch 400, is idle and that the rotary switch 375 is started in operation from the position shown in the drawings, when the wiper 1518 is driven into engagement with its associated third contact, a circuit is completed for energizing the upper winding of the polarized relay R1440. This circuit extends from ground at RA1402 by way of RC1403, RA1436, the upper winding of R1440, C1428, the wiper 1575, C1587, the wiper 1518, the third contact of the set 1508, the contact springs 1507', 1508', 1509', and 1513, to battery as applied to the control conductor of the trunk line incoming to the connector switch 400. When energized over the above-traced circuit the polarized relay R1440 immediately operates to interrupt, at RA1447 and its associated upper contact, the above-traced operating circuit for M1509, thereby to arrest the operation of the switch 375 while the wipers of this switch are standing in the position corresponding to the conversational connector switch 400. At RA1448

and its associated lower contact the relay R1440 completes a path for short-circuiting its upper winding, but this relay does not restore since, when once operated, the energization furnished by its lower winding is sufficient to maintain it in its operated position. At RA1441, the relay R1440 completes a circuit, traced hereinafter, for energizing the vertical magnet corresponding to the trunk line leading to the selected idle conversational connector switch. At its armatures 10 RA1442 to RA1446, inclusive, the relay R1440 connects the extra control leads C1391 to C1395, inclusive, to the wipers 1483 to 1487, inclusive, for a purpose explained subsequently.

In the present case, the vertical magnet VM1510 is energized in response to the operation of R1440, the above-mentioned circuit for energizing this vertical magnet extending from ground at RA1441 by way of C1427, the wiper 1574, C1586, the wiper 1517, and through the winding of VM1510 to battery. When energized over the above-traced circuit, the magnet VM1510 operates to complete, at its armature 1515, a holding circuit for itself, which circuit extends from ground as applied to the control conductor C290. At the armatures 1505 and 1513, the vertical magnet VM1510 completes a circuit, extending from ground on the control conductor C290, for energizing the relay R1520. At its springs 1511, 1512 and 1513 and the respective corresponding springs 1503, 1504, and 1505 of HM1500, the vertical magnet VM1510 connects the trunk line incoming to the selector switch 300 through to the trunk line incoming to the selected conversational connector switch 400. At the springs 1509' and 1513 the vertical magnet VM1510 interrupts a point in the above-traced testing circuit by way of which an idle one of the conversational connector switches of the selected group was selected. At the springs 1514 and 1506, the vertical magnet VM1510 prepares a test circuit, traced hereinafter, which is utilized in positioning the tie switch 325 in the particular one of its positions corresponding to the selected conversational connector switch 400. When the relay R1520 operates it interrupts, at RA1521, a point in the release circuit, traced hereinafter, for energizing the operating magnet M1549 of the rotary switch 475 during the release of the conversational switch train.

Following the operation of VM1510 the tie switch 325 is again started in operation to position its wipers on the contacts corresponding to the selected conversational connector switch 400, it being pointed out that the tie switch 325 like the switch 225 is provided with ten operating positions for each conversational selector switch to which it has access. To initiate the second operation of the tie switch 325, the relay R1440 is arranged so that upon operating it completes an alternative circuit for energizing the operating magnet M1560 of the tie switch. This alternative circuit extends from ground at RA1451 by way of RC1453, C1453 RA1309, RA1361, the wiper 1382, the third contact of the set 1388, C1398, RA1438, RC1438', RA1449, RA1411, RC1413, RA1405, C1426, MA1561, and the winding of M1560 to battery. Due to the circuit interrupting action of the contacts associated with MA1561, the magnet M1560 is repeatedly energized to drive the wipers of the switch 325 to the position corresponding to the connector switch 400 as determined by the above-mentioned alternative test circuit. More particularly, when the wipers noted reach the position corresponding to the switch 400, a second circuit is completed for

energizing the alternating current relay R1150, this circuit extending from the upper terminal of the transformer secondary winding 1167 by way of the winding of R1150, C1146, the wiper 1239, 5 C287, the contact springs 1506 and 1514, C1509, the wiper 1577, C1482, RC1433, RA1431, C1399, the wiper 1383, RA1369, RA1309, C1164 and RA1175 to the opposite terminal of the winding 1167. When energized over the above-traced 10 circuit the relay R1150 operates to interrupt, at RA1151 and RC1153, the above-traced alternative operating circuit for M1560, thereby to arrest the operation of the tie switch 325 while the wipers thereof are standing in the particular 15 position corresponding to the selected conversational connector switch 400. At RA1151 and RC1152, the relay R1150 again completes the above-traced operating circuit for R1340, causing the last mentioned relay to operate to complete, 20 at RA1342, the above-mentioned operating circuit for R1360, which latter circuit extends by way of RA1352, RC1353 and the winding of R1360 to battery. Upon operating, the relay R1360 interrupts, at RA1367 and its associated 25 lower contact, a further point in the above-traced alternative operating circuit for M1560 and, at RA1369, a point in the alternative test circuit as traced above. At RA1366, the relay R1360 opens a point in the above-traced operating circuit for 30 R1340. At RA1362' and RC1364, the relay R1360 interrupts the previously traced circuit over which R1330 is being held energized. Thus the three relays R1150, R1330 and R1340 are caused to restore. At RA1362' and RC1363', the relay 35 R1360 completes a holding circuit for itself, this circuit extending from ground at RA1314 or RA1304 by way of C1154, RA1362', RC1363', and the winding of R1360 to battery. At RA1361 and RC1363, the relay R1360 prepares a test circuit, 40 traced hereinafter, which is subsequently utilized to determine the idle or busy condition of the called line. At RA1365 and its associated upper contact, the relay R1360 completes a circuit for energizing the relay R1410, this circuit extending from battery by way of the resistor 1318, RA1365, the wiper 1381, C1397, RA1447 and its associated 45 lower contact, and the winding of R1410 to ground.

When the relay R1410 operates, it opens, at 50 RA1411 and RC1413, a further point in the above-traced alternative operating circuit for M1560 and, at RA1411 and RC1412, prepares or completes a circuit for energizing the switching-through relay R1530 of the selected connector switch 400 in the event the selected called line is 55 idle. At RA1414 the relay R1410 prepares a circuit, traced hereinafter, for energizing the slow-to-operate relay R1450. At RA1414', the relay R1410 prepares a path, traced hereinafter, for 60 applying ground to the control conductor C1390.

Operation of the apparatus in response to the impulses of the third and fourth digits

During the interval when the operations just 65 described are occurring, the final two line selecting digits may be dialed at the calling substation for the purpose of causing the selected by-path connector switch 450 to operate to the particular position corresponding to the desired 70 called line. The operation of the by-path connector switch 450 in response to the impulses of the final two digits dialed at the calling substation may be completed before or after the operation of the relay R1360 in the manner just described. During the impulses of the third digit 75

dialed at the calling substation A, the line relay R1180 embodied in the second by-path selector switch 350 follows the impulses and repeats the same to the vertical magnet M1424 embodied in the selected by-path connector switch 450. More particularly, during the open circuit period of each impulse of the third digit the line relay R1180 restores to complete a prepared operating circuit for M1424 and the slow-to-release series relay R1420, this circuit extending from ground 1 at RA1181 by way of RC1183, C1158, RA1315, RC1316, C1156, RA1173, C1155, RA1305, RC1306, RA1324 or RA1234, the wiper 1380, C1396, the off-normal springs 1417 and 1416, the winding of R1420 and the winding of M1424 to battery. 1 During each cycle of energization and deenergization occurring during the respective impulses of the third digit, the vertical magnet M1424, in cooperation with its associated ratchet and pawl mechanism, elevates the wipers 1483 to 1487, 2 inclusive, and 1471 and 1472 one step in a vertical direction. Hence, at the conclusion of the third digit, the enumerated wipers are held in a position opposite the level of bank contacts corresponding to the particular subgroup of ten 2 lines which includes the desired called line. At the beginning of the first impulse the relay R1420 3 operates and, due to its slow-to-release characteristic, it remains operated until the series of impulses making up the third digit is completed. 3 When the first step in the vertical direction is taken by the enumerated wipers, the off-normal springs 1416 and 1417 are opened to interrupt a point in the impulsing circuit as traced above. Simultaneously with this operation, however, the 3 off-normal springs 1417 and 1418 are closed so that the impulsing circuit is held intact by way of the last-mentioned springs, RA1421 and RC1422 until the series of impulses is ended. The first time the vertical magnet M1424 4 operates, the off-normal springs 1408 are closed to 4 prepare a circuit, traced hereinafter, for energizing the release magnet M1409. The number of impulses making up the third digit will, of course, depend upon which of the ten subgroups 4 of ten lines includes the called line 1599. If it be assumed, for example, that the called line 1599 is in the second subgroup of ten lines, the third digit will necessarily comprise two impulses so that, at the conclusion of the digit, the wiper 1485 will be left standing in a position opposite the second level of bank contacts, which level includes the contact 1480 terminating the control conductor C1497 of the called line. 5

As pointed out previously, the Strowger mechanism embodied in the switch 450 is provided with two sets 1465 and 1466 of auxiliary contacts, the contacts of which are arranged to be traversed by brushes or wipers 1471 and 1472, respectively, carried by the rotary shaft of the mechanism during the vertical and rotary movements of the shaft, respectively. Thus, during the vertical movement of the shaft just described the brush 1471 is operated two steps so that at the conclusion of the third digit it is left standing in engagement with the contact 1469. The arrangement of the contacts at the set 1465 and of the brush 1471 associated therewith is such that the brush is held in engagement with the selected contact during rotary movement of the wipers. 60 The brush 1472 on the other hand is not affected by vertical movement of the wiper carriage structure but is only driven over the contacts of the associated contact set 1466 during rotary movement of the wipers. On the other hand, the 65 70 75 80 85 90 95

brush 1472 and the contacts of the set 1466 are so arranged that the brush 1472 may engage any of the contacts of the set 1466 during rotary movements of the switch wipers.

5 Shortly following the end of the third digit, the slow-to-release relay R1420 falls back to condition the by-path connector switch 450 to respond to the impulses making up the fourth and final digit dialed at the calling substation. During the dialing of this digit the line relay R1180 again follows the impulses and repeats these impulses to the rotary magnet M1425, thereby to impart rotary movement to the enumerated wipers of the Strowger switching mechanism. More particularly, the rotary magnet M1425 and R1460' are energized in parallel during each impulse of the fourth digit over a circuit extending from ground at RA1181 by way of RC1183, C1158, RA1315, RC1316, C1156, RA1173, C1155, 20 RA1305, RC1306, RA1324 or RA1334, the wiper 1380, C1398, the off-normal springs 1417 and 1418, RA1421 to RC1423 where it divides, one branch extending through the winding of M1425 to battery and the other branch extending 25 through the winding of R1460' to battery. During each impulse, the magnet M1425 functions to step the wipers of the Strowger switching mechanism one step so that at the conclusion of the fourth digit these wipers are left standing in engagement with the contact set of the selected level corresponding to the number of impulses making up the digit. If it be assumed for example, that the called line 1599 corresponds to the third contact set of the selected level, the 30 fourth digit dialed at the calling substation will necessarily comprise three impulses so that at the conclusion thereof the wiper 1485 will be left standing in engagement with the third contact 1480 of the second level, which contact terminates the control or private conductor C1497 of the line 1599. During the fourth digit the brush 1472 is rotated step-by-step so that at the conclusion of the digit it is left standing in engagement with its associated third contact 1470.

The relay R1460' operates at the beginning of the first impulse of the fourth digit end, due to its slow-to-release characteristic, remains operated until the end of the digit. Upon operating, the relay R1460' completes at RA1461' a circuit extending by way of RA1452' for energizing the upper winding of R1450'. The relay R1450', which is of the two-step type, only partially operates when its upper winding is energized, to complete at the "X" contacts associated with RA1453', an obvious path for short-circuiting its lower winding. Shortly following the end of the fourth digit the relay R1460' restores to open, at RA1461', the path short-circuiting the lower winding of R1450', permitting the two windings of the last-mentioned relay to be energized in series. The relay R1450' now completes its operation to open at RA1452' a further point in the path for short-circuiting its lower winding. At RA1451', the relay R1450' completes the above-mentioned path for applying ground to the control conductor C1390, this path extending from ground at RA1414' by way of RA1451' and RA1443' to the control conductor C1390. The completion of this path serves to hold the two relays R1300 and R1400 energized and thus prevents the two by-path switches 350 and 450 from being automatically released before the line selecting operations are fully completed in the conversational connector switch 400. At RA1454',

the relay R1450' either prepares or completes a circuit, traced hereinafter, for energizing the slow-to-operate relay R1450, depending upon whether R1410 has previously operated. At its armatures RA1455' to RA1459', inclusive, the 5 relay R1450' connects the test conductors C1391 to C1395, inclusive, to the test wipers 1483 to 1487, respectively, and in so doing prepares or completes a test circuit for determining the idle or busy condition of the selected called line 1599. 10 In this regard it is reiterated that if a selected line is busy ground is impressed upon the control conductor thereof by the associated cut-off relay whereas if the line is idle battery potential is impressed on the control conductor thereof 15 through the winding of the associated cut-off relay.

After the wipers of the Strowger switching mechanism embodied in the by-path connector switch 450 have been operated to the particular 20 position corresponding to the called line 1599 in response to the impulses of the third and fourth digits and the relay R1450' has fully operated, the operations which occur depend upon whether the tie switch 325 has completed its operation to 25 cause the sequential operation of the two relays R1360 and R1410 in the manner described previously. If the tie switch 325 has not completed its operation so that the relays R1360 and R1410 have not operated, the operation of the 30 relay R1450' is only effective to prepare the test circuit for determining the idle or busy condition of the selected line and to prepare the operating circuit for R1450. On the other hand, if the relay R1450' is not fully operated when 35 R1360 and R1410 are caused sequentially to operate in the manner described above when the operation of the tie switch 325 is completed, the relay R1360 only prepares the line testing circuit and the relay R1410 only prepares the operating 40 circuit for R1450. Irrespective of whether R1450' operates before or after the operation of R1360 and R1410, when all three of these relays are operated, the operating circuit for R1450 is completed and the line testing circuit is completed. 45

As pointed out previously, the busy test relay R1320 is embodied in the second by-path selector switch 350. The test circuit extending to this relay is completed only when the two relays 50 R1360 and R1450' are both operated, this circuit extending in the present case by way of C1497, the contact 1480, the wiper 1485, RA1457', RA1444, and its associated lower contact, C1393, the wiper 1379, RA1361, RC1363, RA1331, RA1332, 55 and the winding of R1320 to battery. It will be noted that for this busy test circuit to be completed the slow-to-release relay R1330 must be operated, whereas the relay R1330 must restore to complete the idle line test circuit to be described subsequently. Hence, the relay R1330 must be deenergized substantially simultaneously with the last of the two relays R1360 and R1450' to operate. To this end the relay R1360 is arranged to interrupt at RA1362' and RC1364 the holding circuit, traced previously, for R1330 when it operates, thus insuring that the relay R1330 will be held energized until after the tie switch 325 completes its operation. On the other hand, if the tie switch 325 completes its operation before the 60 fourth and last digit is fully dialed, the ground pulses transmitted to R1330 serve to hold this relay operated until after the digit is ended and the relay R1450' has fully operated. If the selected called line is busy the presence of ground on the 65 70 75 80 85 90 95 100 105 110 115 120 125 130 135 140 145 150 155 160 165 170 175 180 185 190 195 200 205 210 215 220 225 230 235 control conductor causes the busy test relay to be energized over the circuit traced above. Upon operating, the relay R1320 prepares at RA1321 a holding circuit for itself, which circuit is completed when R1330 restores shortly after the completion of the operating circuit for R1320 and is substantially similar to the operating circuit as traced above, but extends by way of RA1321, RA1332, and the winding of RA1320 to battery. At RA1323, the relay RA1320 opens a point in the circuit, traced hereinafter, for energizing the relay R1170 and, at RA1324, it opens the impulsing circuit, traced previously, extending to the rotary and vertical magnets of the by-path connector switch 450. At RA1322, the relay R1320 completes a circuit for energizing the upper winding of the slow-to-release relay R1210 in series with the upper winding of R1215, this circuit extending from ground as extended to the wiper 1379 over the test circuit, by way of RA1361, RC1363, RA1331, RC1333, RA1322, C1145, the wiper 1238, C286, the upper winding of R1210 and the upper winding of R1215 to battery. Both of the relays R1210 and R1215 operate when their respective upper windings are energized over the above-traced circuit. The relay R1215, upon operating, prepares, at RA1216, a holding circuit for R1210 and completes, at RA1217 and RC1218, a circuit for energizing the slow-to-release relay R1200. The relay R1210, upon operating, completes, at RA1212, a holding circuit as mentioned above, this circuit extending from ground at RA1216 by way of RA1212 and the lower winding of R1210 to battery. At RA1213, the relay R1210 opens a point in the operating circuit for the line switching relay R1260, thereby to prevent the calling line from being connected through to the called line at a time when the last-mentioned line is busy. At RA1211, the relay R1210 completes a path for projecting busy tone current to the loop extending back to the calling subscriber's substation, thereby to indicate to the calling party that the calling connection can not immediately be established.

When the relay R1200 operates it connects, at its armatures RA1201 and RA1204 and their respective associated contacts RC1203 and RC1206, the calling subscriber's loop circuit through to the line relay R1215, thereby to hold this relay operated independently of the by-path switch train and so long as the calling subscriber retains his receiver off its hook. At these same armatures and their respective associated upper contacts RC1202 and RC1205 the relay R1200 interrupts the loop circuit extending to the by-path selector switch 350, thereby to cause the sequential restoration of the line relay R1180 and the hold relay R1310 in the order named and in an obvious manner. At this time the by-path switch train comprising the operated by-path switches 350 and 450 is held operated through the continued energization of the two relays R1300 and R1400. At RA1207 and RA1207', the relay R1200 applies multiple ground to the control conductor C283, thereby to hold the conversational switches 100, 200 and 300 operated. At RA1209, the relay R1200 prepares a multiple holding circuit for R1210. At RA1209', the relay R1200 completes a circuit extending by way of RA1259' for energizing the slow-to-release relay R1240. When R1240 operates it completes, at RA1241 and RA1242, an alternative path extending by way of RA1258 for maintaining ground on the hold or control conductor C283. Following the operation of R1240 no further operations occur until

the connection is cleared out at the calling subscriber's substation to initiate the release of the switch train in the manner pointed out in detail hereinafter.

As stated previously, if the called line is idle at the time it is selected by the by-path connector switch 450, battery is present on the control conductor thereof so that the circuit for energizing the busy test relay R1320 is not completed. Shortly after the busy test circuit is completed, the slow-to-release relay R1330 restores and the lower winding of R1170 is energized over the line test circuit. Specifically, the circuit for energizing the lower winding of R1170 extends, in the present case, from battery as applied to the wiper 1379 over the test circuit traced previously, by way of RA1361, RC1363, RA1331, RC1333, RA1323, C1149, and the lower winding of R1170 to ground. The relay R1170 operates when its lower winding is energized over this circuit and completes, at RA1172, a holding circuit for itself, which holding circuit extends from the grounded control conductor C1147 by way of RA1172 and the upper winding of R1170 to battery. At RA1173, the relay R1170 opens a further point in the impulsing circuit, traced previously, by way of which impulses were repeated to the vertical and rotary magnets of the switch 450. At RA1175, the relay R1170 opens a point in the common portion of the two test circuits by way of which R1150 was energized.

At RA1171, the relay R1170 completes a circuit for energizing the upper winding of the line relay R1215, this circuit extending from ground at RA1122 by way of RA1161, RA1171, C1129, the switch wiper 1237, C285, and the upper winding of R1215 to battery. When the relay R1215 operates it causes the sequential operation of R1200 and R1240 in the manner just described and these relays, upon operating, perform their indicated functions as outlined above. In this case the busy relay R1210 is not energized and, hence, when R1200 operates a circuit is completed for energizing R1260, this circuit extending from ground at RA1209' by way of RA1213 and the winding of R1260 to battery. The relay R1260, upon operating, completes, at RA1266, a holding circuit for itself, this circuit extending from ground at RA1216 by way of RA1266 and the winding of R1260 to battery. At RA1261 and RA1263 the relay R1260 further prepares the talking circuit between the calling and called substations and in so doing causes ringing voltage to be impressed across the line conductors C288 and C289. At RA1262, the relay R1260 prepares a circuit for conducting ringing current by way of the calling loop to provide a ring-back tone signal. At RA1264 and RA1265 the relay R1260, upon operating, directly applies ground to the control conductor C290 of the trunk line incoming to the second conversational selector switch 300, thereby to hold this switch and the succeeding connector switch 400 operated independently of the condition of the relays R1215 and R1200 after the call is answered.

When the idle-line-test relay R1170 operates, it also functions to complete a circuit for energizing the line switching relay R1530, this circuit extending from ground at RA1174 by way of C1162, RA1387 and its associated upper contact, the wiper 1382, C1398, RA1438, RC1438', RA1449, RA1441, RC1442, C1495, the wiper 1584, C1596, RC1535', RA1535, and the winding of R1530 to battery. Upon operating the relay R1530 completes, at RA1534 and RA1535, a hold-

ing circuit for itself, this circuit extending from the grounded control conductor C290 by way of the springs 1505 and 1513, RA1534, RA1535, and the winding of R1530 to battery. At RA1531 and 6 RA1532 the relay R1530 further prepares the talking loop between the called and calling subscribers' substations and at RA1533 it prepares a further point in the path, traced hereinafter, for applying ground to the control conductor C1497 10 of the called line 1599.

During the interval when the line testing operations are being performed in the manner just described, the small rotary switch 1460 is operating to cause the energization of the horizontal and vertical magnets embodied in the connector switch 400 which respectively correspond to the vertical and rotary positions occupied by the wiper of the Strowger mechanism embodied in the by-path connector switch 450. More particularly, when both of the relays R1360 and R1450' are operated, a circuit is completed for energizing the slow-to-operate relay R1450, this circuit extending from ground at RA1414 by way of RA1454', the armature 1455 and the winding of R1450 to battery. When energized over the above-traced circuit R1450 operates, after an interval, to complete, at RA1452, an obvious circuit for energizing the operating magnet M1454 embodied in the rotary switch 1460. When energized over this circuit, M1454 operates to step the wipers 1463 and 1464 one step off normal or into engagement with their respective associated first contacts. When this first step is taken by the switch wipers, the off-normal springs 1456 are closed to prepare a circuit for energizing the relay R1450 during the release of the by-path connector switch 450. The off-normal springs 1456' are also closed when the switch wipers 1463 and 1464 are stepped to the first off-normal position. At the last-mentioned off-normal springs, a circuit is completed for energizing the upper winding of R1440', this circuit extending from ground at RA1414 by way of RA1454', the springs 1456', RA1441' and the upper winding of R1440' to battery. The relay R1440' is of the two-step type and only operates to close the "X" contacts associated with RA1462' when its upper winding is energized. When these "X" contacts are closed, the lower winding of R1440' is short-circuited over a path extending from ground at RA1402 by way of RC1403, RA1442', the lower winding of R1440', RA1441', the springs 1456' and RA1454' back to ground at RA1414. At its armature 1455, the magnet M1454, upon operating, interrupts a point in the above-traced operating circuit for the relay R1450, causing this relay to restore to interrupt, at RA1452, the operating circuit for the magnet M1454. When deenergized, this magnet restores its armature 1455 to again complete the operating circuit for R1450, which relay, upon operating a second time, again completes the operating circuit for M1454. Through the interrelated operation of R1450 and M1454, the wipers 1463 and 1464 are successively stepped into engagement with successive ones of their respective associated contacts. Each time the relay R1450 operates to complete the circuit for energizing M1454, it also completes a circuit for energizing the operating magnet M1549 embodied in the rotary switch 475, this latter circuit extending from ground at RA1451 by way of C1496, the wiper 1585, C1597, and the winding of M1549 to battery. Thus, the wipers 1547 and 1548 of the switch 475 are operated in synchronism with

the wipers 1463 and 1464 of the switch 1460 so that at any particular point in the operation of the two switches the respective wipers noted stand in engagement with corresponding contacts of their respective associated contact sets. When the wipers 1547 and 1548 of the switch 475 are stepped one step off normal the off-normal springs 1556 are closed to prepare a circuit for energizing M1549 during the release of the connector switch 400. During the operation of the two switches 475 and 1460 and when the wiper 1463 is driven into engagement with the contact of the set 1461 which is connected to the grounded wiper 1471 of the operated Strowger switching mechanism, a circuit is completed for energizing the particular horizontal magnet which corresponds to the grounded contact of the set 1461, or to the particular subgroup of ten lines which includes the called line 1599.

In the present case wherein the wiper 1471 is left standing in engagement with its associated second contact 1469 at the end of the fourth and final digit dialed at the calling substation, the horizontal magnet HM1540 is energized when the wiper 1463 is driven into engagement with its associated second contact. Specifically, the circuit for energizing HM1540 extends from ground at the wiper 1471 by way of the contact 1469, the second contact of the set 1461, the wiper 1463, C1524, the wiper 1522, C1526, the wiper 1548, the second contact of the set 1546 and the winding of HM1540 to battery. When energized over the above-traced circuit HM1540 attracts its operating armature to complete at the armature spring 1541 a holding circuit for itself, this holding circuit extending from the grounded control conductor C290 by way of the switch springs 1505 and 1513, the armature spring 1541, and the winding of HM 1540 to battery. When the horizontal magnet HM1540 operates to move its associated operating bar to the off-normal position, the line switching contact springs, including the springs 1542, 1543, and 1544, are moved to a position to be engaged by the respective associated contact springs controlled by the various vertical magnets.

During the synchronous operation of the two rotary switches 475 and 1460, a circuit is also completed for energizing the particular vertical magnet of the connector switch 400 which corresponds to the called line of the selected subgroup. More particularly, when the wiper 1464 is driven into engagement with its associated third contact a circuit is completed for energizing the vertical magnet VM1550 which corresponds to the called line 1599. This circuit extends from ground as applied to the wiper 1472 by way of the contact 1479 engaged by this wiper, the third contact of the set 1462, the wiper 1464, C1525, the wiper 1523, C1527, the wiper 1547, the third contact of the set 1545, and the winding of VM1550 to battery. When energized over the above-traced circuit VM1550 attracts its operating armature and in so doing completes at the armature spring 1554 a holding circuit for itself, which circuit extends by way of the grounded control conductor C290, the switch springs 1505 and 1513, the armature 1554 and the winding of VM1550 to battery. At the springs 1551, 1552, and 1553 the vertical magnet VM1550 connects the conductors of the trunk incoming to the switch 400 through to the conductors of the called line 1599. This last-mentioned operation results in the extension of ground by way of the springs 1544 and 1553 to the control conductor of 75

the called line 1599. As a consequence the cut-off relay embodied in the line circuit terminating this line is held operated and the line is marked as busy in the bank contacts of the by-path connector switches to which it extends.

Ringing the called substation

When the line conductors of the trunk line incoming to the connector switch 400 are connected through to the conductors of the called line 1599, ringing current is projected over the called line to energize the signal device at the called substation. The path of this current extends from the ungrounded terminal of the ringing current generator, not shown, by way of the exchange battery, the upper winding of R1250, RC1252, RA1251, RA1261, C286, the switch springs 1503 and 1511, RA1231, the switch springs 1542 and 1551, the negative side of the called line 1599, 10 the bridged condenser and ringing device at the called substation, the positive side of the called line, the switch springs 1552 and 1543, RA1532, the switch springs 1512 and 1504, C289, RA1263 and RA1254 to the grounded terminal of the 15 ringing current generator at RC1255. The resulting operation of the ringing device provided at the called substation B gives an audible indication that the substation B is being called. A portion of the ringing current is by-passed by way 20 of RA1262, the condenser 292, the condenser 293, the upper side of the calling loop circuit, the receiver at the calling substation, the lower side of the calling loop circuit, the condenser 294 and the lower winding of R1220 to ground. The resulting energization of the receiver at the calling substation provides a ring-back tone which indicates to the calling party that the called substation is being rung.

Operation of the apparatus when the called party answers

When the call is answered at the called substation, a direct current bridge is placed across the conductors of the called line 1599 in the usual manner to complete a circuit for energizing the slow-acting ring cut-off relay R1250, this circuit being substantially identical with that traced above and traversed by the ringing current. Upon operating, the relay R1250 completes at RA1259 a holding circuit for itself, this circuit extending from ground at RA1216 by way of RA1266, RA1213, RA1259', RA1259, and the lower winding of R1250 to battery. At its armatures RA1251 and RA1254 and their respective associated contacts RC1252 and RC1255, the relay R1250, upon operating, opens two points in the above-traced path for projecting ringing current over the called loop to the ringing device at the called substation, which path also comprises a part of the operating circuit for R1250. At these same armatures and their respective associated contacts RC1253 and RC1256 the relay R1250 completes a talking connection between the calling and called substations and in so doing extends 60 the called substation loop circuit back to the windings of the battery reversing relay R1220 to cause the energization and operation of this latter relay. At RA1257 and RA1258 the relay R1250 applies booster battery potential to the 65 control conductor C283 for the purpose of operating a call registering device, a coin collecting mechanism, or the like.

When the battery reversing relay R1220 operates its armatures RA1221 to RA1224, inclusive, 70 it reverses the polarity of the talking battery volt-

age applied to the line conductors extending to the calling substation, this voltage being derived through the windings of the line relay R1215 in the usual manner. At RA1225 and RA1227, the relay R1220 completes multiple holding circuits 5 for the two relays R1260 and R1259, respectively, thereby to render the restoration of these relays under the control of the called party. Shortly following the operation of R1250, the slow-to-release relay R1240 restores to open at RA1241 10 and RA1242 the path for applying booster battery potential to the control conductor C283. At the springs RA1242 and RC1242' ground is applied to C283 simultaneously with the removal of booster battery from the control conductor. Following 15 the restoration of R1240, no further operation of the apparatus occurs until the connection is cleared out at one or both of the calling and called substations.

Release of the by-path second selector and connector switches

As pointed out above, when the relay R1200 operates it interrupts at RA1201 and RA1204 and their respective associated contacts RC1202 and 25 RC1205 two points in the circuit over which the line relay R1180 is being held energized, causing the two relays R1180 and R1310 to restore in the order named. More particularly, when R1180 restores, it interrupts at RA1181 and RC1182 the 30 circuit over which the hold relay R1310 is being held energized and prepares, at RA1181 and RC1183, the circuit for energizing the release magnet M1373. When, shortly thereafter, R1310 restores, it further prepares, at RA1315 and 35 RC1317, the circuit for energizing the release magnet M1373. At RA1311, the relay R1310 opens a point in the operating circuit for R1300. At RA1312, the relay R1310 opens the original holding circuit for R1300. At RA1313, the relay 40 R1310 opens the multiple path for applying ground to C1147 and in so doing opens a further point in the operating circuit for R1300. At RA1314, the relay R1310 opens the multiple path for applying ground to the hold conductor C1154. 45

In the usual case the small rotary switch 1460 does not complete its operation to cause the energization of the selected horizontal and vertical magnets of the selected conversational connector switch, as for example the switch 400, before the 50 hold relay R1310 restores. It is for this reason that the relay R1450' is arranged to complete the multiple path traced previously for retaining ground on the control conductor C1390 to hold the two relays R1300 and R1400 energized. So 55 long as the two last-mentioned relays are energized, the by-path switches 350 and 450 are prevented from releasing. After the wipers of the switch 1460 have been driven over all of their respective associated contacts, the selected horizontal and vertical magnets of the selected conversational connector switch are energized and locked up and the by-path switch train is of no further use in completing the connection. For the purpose of releasing the operated by-path 60 switches, the switch 1460 is arranged to cause the relay R1440' to complete its operation after the wipers 1463 and 1464 have been driven over all of their respective associated contacts. More particularly, when the indicated wipers are returned 65 to their respective home positions, the off-normal springs 1456' are opened for an interval to interrupt the above-traced path short-circuiting the lower winding of R1440'. The relay R1440' now fully operates to open, at RA1443', a point 70

in the above-traced path for retaining ground on the control conductor C1390. When ground is removed from C1390 the relays R1170, R1300 and R1400 are deenergized and restore.

Upon restoring, the relay R1300 completes the circuit for energizing the release magnet M1373, this circuit extending from ground at RA1181 by way of RC1183, C1158, RA1315, RC1317, RA1308', the off-normal springs 1376, and the winding of M1373 to battery. When energized over this circuit the release magnet M1373 operates to cause the wipers 1378 to 1383, inclusive, to be returned to rotary and vertical normal in the usual manner. When these wipers are returned to normal, the off-normal springs 1376 and 1377 are opened and the off-normal springs 1375 are closed. When the springs 1376 are opened the operating circuit for the release magnet is interrupted in the usual manner. At RA1304, the relay R1300 interrupts the respective holding circuits for the operated relays R1100, R1120, R1130, R1350 and R1360 causing all of these relays to restore. Thus, the by-path selector switch 350 is fully released.

When the relay R1360 falls back it interrupts, at RA1365, the operating circuit for R1410 causing the last-mentioned relay to restore to open, at RA1414, the operating circuit for R1450. Substantially simultaneously with the restoration of R1410 the relay R1400 restores to complete an alternative circuit for energizing R1450, this alternative circuit extending from ground at RA1406 by way of the off-normal springs 1456, the armature 1455 and the winding of R1450 to battery. Thus, the interrelated operation of R1450 and M1454 continues until the wipers 1463 and 1464 are again driven to the home position at which time the off-normal springs 1456 are opened. When the springs 1456 are opened, the alternative operating circuit for R1450 is interrupted and the interrelated operation of this relay and M1454 is arrested.

When the relay R1400 falls back, it opens, at RA1402 and RC1403, a point in the common portion of the holding circuits for the relays R1430, R1440, R1440' and R1450', causing all of these relays to restore. At RA1402 and RC1404, the relay R1400, upon restoring, completes a circuit extending by way of the off-normal springs 1408 for energizing the release magnet M1409. The resulting operation of this release magnet causes the wipers of the Strowger mechanism embodied in the switch 450 to be returned to rotary and vertical normal in the usual manner. When this occurs, the off-normal springs 1417 and 1418 are opened, the off-normal springs 1416 and 1417 are closed, and the off-normal springs 1408 are opened to interrupt the circuit for energizing M1409. Thus, the by-path connector switch 450 is fully released.

In the event the calling party abandons the call after the second or the third digit is dialed, but before the final digit is dialed, the operated by-path switches 350 and 450 are released in a manner substantially similar to that just described. In this case, however, the two relays R1440' and R1450' are not caused to operate. Hence, the line testing circuits traced previously are not completed and the path controlled by the two indicated relays for applying multiple ground to the control conductor C1390 is not completed. Accordingly, neither of the two line test relays R1320 and R1170 is caused to operate and the release of the by-path switch train is under the control of the calling party. More particularly, when the calling party hangs up, the relays

R1180, R1310 and R1300 are caused to restore in the order named. When the two last-named relays restore, the other release operations occur in the exact manner described in detail above, it being pointed out that, when R1100 falls back in response to the removal of ground from C1154, ground is removed from the control conductor C283 to initiate the release of the operated conversational switches in the manner pointed out in detail immediately hereinafter.

Release of the conversational switch train

As indicated previously, the operated conversational switch train is only completely released when the connection is cleared out at both the calling and called substations. Thus, the operated horizontal and vertical magnets of the two operated switches 100 and 200 are held energized over their respective holding circuits which commonly include the control conductor C283, ground potential being applied to this conductor by way of RA1242', RA1242, RA1207 and RA1207', for the duration of the conversation and until the connection is cleared out at the calling substation. In a similar manner the operated horizontal and vertical magnets of the second selector switch 300 and the connector switch 400 are held energized over their respective holding circuits which commonly include the control or hold conductor C290, ground being retained on this conductor for the duration of the call through the continued energization of R1260. The by-path switches utilized in setting up the connection, as was pointed out above, are successively released as the establishment of the connection progresses, the two switches 350 and 450 being released following the complete operation of the conversational connector switch 400.

Assuming that the calling party is the first to hang up, the two operated switches 100 and 200 are alone released, the remaining operated switches 300 and 400 being held operated until the connection is thereafter cleared out at the called substation. More particularly, when the subscriber at the substation A hangs up before the called subscriber at the substation B restores his receiver to its hook, the loop circuit over which the line relay R1215 is held operated is interrupted, causing this relay to restore. Upon restoring, the relay R1215 interrupts at RA1217 and RC1218 the operating circuit for the slow-to-release relay R1200. The last-mentioned relay restores after an interval to remove, at RA1207 and RA1207', ground from the control conductor C283, thereby to interrupt the holding circuits for each of the operated horizontal and vertical magnets HM120, VM130, HM1270 and VM1280. As a consequence, all of these magnets are deenergized and their respective associated armatures are returned to normal. At RA1207' battery potential is applied by way of the resistor 291 to the control conductor C283, thereby to mark the second conversational selector switch 300 as idle. During the interval between the restoration of R1215 and the restoration of R1200 a circuit is completed for energizing R1210, this circuit extending from ground at RA1217 by way of RC1219, RA1209, RA1244 and the lower winding of R1210 to battery. Upon operating, the relay R1210 completes, at RA1212, an obvious holding circuit for itself. At RA1211, the relay R1210 completes a path for impressing busy-tone voltage on the loop extending to the called substation. Following the restoration of R1210

R1215 and R1200 and the operation of R1210, no further operations occur in the second selector switch until the called subscriber hangs up. When ground potential is removed from the hold conductor C283 the holding circuit for the cut-off relay R710 associated with the calling line 772 is interrupted, causing this relay to restore to remove ground potential from the control conductor C775 of the calling line. When ground potential is removed from the control conductor C775 in the manner noted, negative battery potential is extended through the winding of R710 to this control conductor, thereby to mark the calling line as idle.

15 When the call is cleared out at the called substation the loop circuit extending to this substation is interrupted to cause the restoration of the battery reversing relay R1220. Upon restoring, the last-mentioned relay interrupts, at 20 RAI225 and RAI227, the respective holding circuits for R1210, R1260 and R1250, causing these relays to restore. Upon restoring, the relay R1260 removes ground from the control or hold conductor C290, thereby to interrupt the holding circuits for the operated horizontal and vertical magnets in the two switches 300 and 400. As a consequence, the magnets HM1500, VM1510, 25 HM1540 and VM1550 are all deenergized and their respective associated armatures are restored to normal. The removal of ground from the hold conductor C290 also results in the deenergization of the relays R1520 and R1530 causing these two relays to restore. When R1520 falls back, it completes, at RAI521, a circuit for energizing the operating magnet M1549 of the 30 switch 475, this circuit extending from ground at RAI521 by way of the off-normal springs 1556, the armature 1555 and the winding of the magnet M1549 to battery. Due to the circuit interrupting action of the contacts associated with the armature 1555, the magnet M1549 operates to 35 drive the wipers 1547 and 1548 to their respective home positions, at which time the off-normal springs 1556 are opened to interrupt the operating circuit for M1549.

40 It will be apparent from the foregoing description that when ground is removed from the hold conductor C290 it is also removed from the control conductor C1497 of the called line 1599. The removal of the ground from this control conductor results in the deenergization of the cut-off relay provided in the line circuit terminating the line 1599 and in the application of battery potential to the control conductor noted. Thus, 45 the called line 1599 is marked as idle in the bank contacts of the by-path connector switches to which it extends.

50 In the event the called subscriber hangs up before the connection is cleared out at the calling substation, only the battery reversing relay R1220 is caused to restore, the entire switch train being held operated through the continued energization of the line relay R1215. Thereafter, and when the calling subscriber hangs up to cause the restoration of R1215, the operated switches are released in a manner identical with that just described. In this latter case, however, ground potential is substantially simultaneously removed from the two hold conductors C283 and C280 and thus the release of the four operated conversational switches 100, 200, 300 and 400 is 55 accomplished at the same time.

60 The manner in which a partially established connection is released when a calling subscriber hangs up following the receipt of busy tone is

substantially similar to that set forth in the immediately preceding paragraphs. In this regard it will be recalled that when a line is tested and found busy the relays R1210, R1215, R1200 and R1240 of the second conversational selector switch 300 are caused to operate and that the remaining control relays R1220, R1250 and R1260 are not energized. With the apparatus in this condition and when the loop circuit is interrupted at the calling substation, the line relay R1215 restores to initiate the restoration of the three relays R1200, R1210 and R1240. When R1200 falls back it removes, at RAI201 and RAI201', ground potential from the two control conductors C283 and C290, thereby to cause the 15 release of the operated switches 100, 200, 300 and 400 and the respective line circuits associated with the calling and called lines in the exact manner set forth above.

20 While there has been described what is at present considered to be the preferred embodiment of the invention, it will be understood that various modifications may be made in the circuits thereof and it is intended in the appended claims to cover all such modifications as fall within the true spirit and scope of the invention.

25 What is claimed is:

1. In a switching system of the type wherein the setting up of connections by way of main switches in successive switching stages is controlled by the preliminary setting up of connections to successive stages of a paralleling system of by-pass switches, a plurality of main switches of the crossbar type, each of said main switches including a plurality of horizontal operating magnets and a plurality of vertical operating magnets, a plurality of automatic by-pass switches, and means including said by-pass switches for causing the successive operation of a selected horizontal magnet and a selected vertical magnet in each of a plurality of said main switches, whereby a connection is routed by way of said last-named main switches.

2. In a telephone system, a plurality of lines, and a switching system for setting up connections between said lines, said switching system being of the type wherein the setting up of connections by way of main switches in successive switching stages is controlled by the preliminary setting up of connections to successive stages of a paralleling system of by-pass switches and including a plurality of main switches of the crossbar type, said switches being arranged to be connected in tandem to set up connections between said lines, each of said switches including two sets of operating magnets, a plurality of automatic by-pass switches, and means including said by-pass switches for causing the operation of an operating magnet in each set of a plurality of tandem arranged main switches, thereby to cause a connection to be routed from one of said lines through said plurality of main switches to a second of said lines.

3. In a telephone system, a plurality of lines, and a switching system for setting up connections between said lines, said switching system being of the type wherein the setting up of connections by way of main switches in successive switching stages is controlled by the preliminary setting up of connections to successive stages of a paralleling system of by-pass switches and including a plurality of main switches of the crossbar type, said switches being arranged to be connected in tandem to set up connections between said lines, each of said switches including a plurality of op-

erating magnets, a plurality of automatic bypass switches, a plurality of tie switches for operatively associating said by-pass switches with said main switches, and circuits for selectively energizing the operating magnets of said main switches, said circuits being arranged to extend by way of said tie switches and being controllable from said by-pass switches.

4. In a switching system of the type wherein the setting up of connections by way of main switches in successive switching stages is controlled by the preliminary setting up of connections to successive stages of a paralleling system of by-pass switches, a main switch of the cross-bar type, a plurality of lines accessible to said main switch and divided into groups, two sets of operating magnets in said switch, the magnets of one set individually corresponding to different groups of said lines and the magnets of the other set individually corresponding to the lines of each group, and means included in at least one of said by-pass switches for causing a selected one of the magnets of each of said sets to be operated, whereby said main switch is operated to select a particular one of said lines.

5. In a by-pass switching system, a main switch of the crossbar type, a plurality of lines accessible to said switch and divided into groups, two sets of operating magnets included in said switch, the magnets of one set individually corresponding to different groups of said lines and the magnets of the other set individually corresponding to the lines of each group, a by-pass selector switch corresponding to one of said groups of lines, means operative to seize said main switch and said selector switch, means included in said selector switch and operative in response to the seizure of said selector switch for causing the operation of the magnet of said one set which corresponds to said one group of lines, means responsive to the operation of said last-named magnet for selecting one of the lines of said one group, and means included in said by-pass switch and operative in response to the selection of said one line for causing the operation of the magnet of said other set which corresponds to said one line.

6. In a by-pass switching system, a plurality of main switches of the crossbar type, a plurality of lines accessible to said switches and divided into groups, two sets of operating magnets included in each of said switches, the magnets of one set in each switch individually corresponding to different groups of said lines and the magnets of the other set in each switch individually corresponding to the lines in each group, a by-pass selector switch corresponding to a particular one of said groups of lines, a tie switch associated with said selector switch and having operating positions individually corresponding to said main switches and to the lines of said one group, means operative to seize one of said main switches and said selector switch, means responsive to the seizure of said selector switch for causing said tie switch to operate to the position corresponding to said one main switch, means responsive to the operation of said tie switch to said last-named position for causing the operation of the magnet in said one main switch which corresponds to said one group of lines, means responsive to the operation of said last-named magnet for selecting a particular line in said one group, and means responsive to the selection of said particular line for causing the operation of the

magnet in said one main switch which corresponds to said one line.

7. In a by-pass switching system, a plurality of main switches of the crossbar type, a plurality of lines accessible to said switches and divided into groups, two sets of operating magnets included in each of said switches, the magnets of one set in each switch individually corresponding to different groups of said lines and the magnets of the other set in each switch individually corresponding to the lines in each group, a by-pass selector switch corresponding to a particular one of said groups of lines, a tie switch associated with said selector switch and having operating positions individually corresponding to said main switches and to the lines of said one group, means operative to seize one of said main switches and said selector switch, means responsive to the seizure of said selector switch for causing said tie switch to operate to the position corresponding to said one main switch, means responsive to the operation of said tie switch to said last-named position for causing the operation of the magnet in said one main switch which corresponds to said one group of lines, means responsive to the operation of said last-named magnet for selecting a particular line in said group, means responsive to the selection of said particular line for causing the operation of the magnet in said one main switch which corresponds to said one line, and means operative in response to the operation of said last-mentioned means for causing said tie switch to operate to the position corresponding to said one line.

8. In a by-pass switching system, a plurality of main switches of the cross-bar type, a plurality of lines accessible to said switches and divided into groups, two sets of operating magnets included in each of said switches, the magnets of one set in each switch individually corresponding to different groups of said lines and the magnets of the other set in each switch individually corresponding to the lines in each group, a by-pass selector switch corresponding to a particular one of said groups of lines, a tie switch associated with said selector switch and having operating positions individually corresponding to said main switches and to the lines of said one group, means operative to seize one of said main switches and said selector switch, means responsive to the seizure of said selector switch for causing said tie switch to operate to the position corresponding to said one main switch, means responsive to the operation of said tie switch to said last-named position for arresting the operation of said tie switch and for causing the operation of the magnet in said one main switch which corresponds to said one group of lines, means responsive to the operation of said last-named magnet for selecting a particular line in said one group, means responsive to the selection of said particular line for causing the operation of the magnet in said one main switch which corresponds to said one line, means operative in response to the operation of said last-named means for again initiating the operation of said tie switch, and means operative when said tie switch is operated to the position corresponding to said one line for arresting the operation of said tie switch.

9. In a by-pass switching system, a plurality of main switches of the crossbar type, a plurality of lines accessible to said switches and divided into groups, two sets of operating magnets included in each of said switches, the magnets of one set in

each switch individually corresponding to different groups of said lines and the magnets of the other set in each switch individually corresponding to the lines in each group, each of said main switches including a test switch having operating positions individually corresponding to the lines forming any one of said groups, a by-pass selector switch corresponding to one group of said lines, a tie switch associated with said by-pass selector switch and having operating positions individually corresponding to said main switches and to the lines of said one group, means operative to seize one of said main switches and said selector switch, means responsive to the seizure of said selector switch for causing said tie switch to operate to the position corresponding to said one main switch, means responsive to the operation of said tie switch to said last-named position for causing the operation of the magnet in said one main switch which corresponds to said one group of lines, means responsive to the operation of said last-named magnet for operatively associating the lines of said one group with the test which included in said one main switch, means also responsive to the operation of said last-named magnet for causing said test switch to operate to a position corresponding to an idle one of said one group of lines, means responsive to the operation of said last-named test switch to said last-named position for causing the operation of the magnet in said one main switch which corresponds to said one line, and means responsive to the operation of said last-named means for causing said tie switch to operate to the position corresponding to said one line.

10. In a by-pass switching system, a plurality of main switches of the crossbar type, a plurality of lines accessible to said switches and divided into groups, two sets of operating magnets in each of said switches, the magnets of one set in each switch individually corresponding to different groups of said lines and the magnets of the other set in each switch individually corresponding to the lines in each group, each of said main switches including a test switch having operating positions individually corresponding to the lines forming any one of said groups, a by-pass selector switch corresponding to one group of said lines, a tie switch associated with said by-pass selector switch and having operating positions individually corresponding to said main switches and to the lines of said one group, means operative to seize one of said main switches and said selector switch, means responsive to the seizure of said selector switch for causing said tie switch to operate to the position corresponding to said one main switch, means responsive to the operation of said tie switch to said last-named position for arresting the operation of said tie switch and for causing the operation of the magnet in said one main switch which corresponds to said one group of lines, means responsive to the operation of said last-named magnet for operatively associating the lines of said one group with the test switch in said one main switch, means also responsive to the operation of said last-named magnet for initiating the operation of said last-named test switch, means operative when said last-named test switch is operated to a position corresponding to an idle one of said one group of lines for arresting the operation of said last-named test switch and for causing the operation of the magnet in said one main switch which corresponds to said one line, means responsive to the

operation of said last-named means for again initiating the operation of said tie switch, and means operative when said tie switch is operated to the position corresponding to said one line for arresting the operation of said tie switch.

11. In a by-pass switching system, a plurality of main switches of the crossbar type, a plurality of lines accessible to said switches and divided into groups, two sets of operating magnets in each of said switches, the magnets of one set in each switch individually corresponding to different groups of said lines and the magnets of the other set in each switch individually corresponding to the lines in each group, a by-pass selector switch including a test relay, a tie switch associated with said by-pass selector switch and having operating positions individually corresponding to said main switches and to the lines of one of said groups, means operative to seize said selector switch and one of said main switches, means responsive to the seizure of said selector switch for initiating the operation of said tie switch, a test circuit for said test relay, said test circuit being so connected and arranged that said test relay operates from one of its two positions to the other when said tie switch is operated to the position corresponding to said one main switch, means responsive to the operation of said test relay to its said one position for causing the operation of the magnet in said one main switch which corresponds to said one group of lines, said test relay being operative from its other position to its one position in response to the operation of said last-mentioned magnet, means responsive to the last-mentioned operation of said test relay for selecting an idle one of the lines of said one group, means operative when said one line is selected for causing the operation of the magnet in said one main switch which corresponds to said one line and for again initiating the operation of said tie switch, a second test circuit for said test relay, said second test circuit being so connected and arranged that said test relay operates from its one position to its other position when said tie switch is operated to the position corresponding to said one line, and means responsive to the last-mentioned operation of said test relay for arresting the operation of said tie switch.

12. In a by-pass switching system, a plurality of main switches of the crossbar type, a plurality of lines accessible to said switches and divided into groups, two sets of operating magnets in each of said switches, the magnets of one set in each switch individually corresponding to different groups of said lines and the magnets of the other set in each switch individually corresponding to the lines in each group, a by-pass selector switch including a test relay, a tie switch associated with said by-pass selector switch and having operating positions individually corresponding to said main switches and to the lines of one of said groups, means operative to seize said selector switch and one of said main switches, means responsive to the seizure of said selector switch for initiating the operation of said tie switch, a test circuit for said test relay, said test circuit being so connected and arranged that said test relay is energized thereover and operates when said tie switch is operated to the position corresponding to said one main switch, means responsive to the operation of said test relay for arresting the operation of said tie switch and for causing the operation of the magnet in said one main switch which corresponds to said one group of lines, means responsive to the

- 5 sive to the operation of said last-named magnet for interrupting said test circuit, thereby to de-energize said test relay, means operative in response to the resulting restoration of said test relay for selecting an idle one of the lines in said one group, means operative when said one line is selected for causing the operation of the magnet in said one main switch which corresponds to said one line and for again initiating the operation 10 of said tie switch, a second test circuit for said test relay, said second test circuit being so connected and arranged that said test relay is energized and operates when said tie switch is operated to the position corresponding to said one line, and means responsive to the last-named operation of said test relay for arresting the operation of said tie switch.
- 15 13. In a by-pass switching system, a plurality of first switches, a plurality of groups of second switches accessible to said first switches, a by-pass selector switch corresponding to the second switches forming one of said groups, a tie switch associated with said by-pass selector switch and having operating positions individually corresponding to said first switches and to the second switches forming one of said groups, means operative to seize one of said first switches and said selector switch, means responsive to the seizure of said selector switch for causing said tie switch to operate to a position corresponding to said one first switch, means responsive to the operation of said tie switch to said last-named position for causing the partial operation of said one first switch, means responsive to the partial operation of said one first switch for selecting an idle one of said one group of second switches, means responsive to the selection of said one second switch for causing said one first switch to complete its operation, thereby to seize said one second switch, and means responsive to the operation of said last-named means for causing said tie switch to operate to the position corresponding to said one of said second switches.
- 20 14. In a by-pass switching system, a plurality of first switches, a plurality of groups of second switches accessible to said first switches, a by-pass selector switch corresponding to the second switches forming one of said groups, a tie switch associated with said by-pass selector switch and having operating positions individually corresponding to said first switches and to the second switches forming one of said groups, means operative to seize one of said first switches and said selector switch, means responsive to the seizure of said selector switch for causing said tie switch to operate to a position corresponding to said one first switch, means responsive to the operation of said tie switch to said last-named position for causing the partial operation of said one first switch, means responsive to the partial operation of said one first switch for selecting an idle one of said one group of second switches, means responsive to the selection of said one second switch for causing said one first switch to complete its operation, thereby to seize said one second switch, and means responsive to the operation of said last-named means for causing said tie switch to operate to the position corresponding to said one of said second switches.
- 25 15. In a by-pass switching system, a plurality of first switches, a plurality of groups of second switches accessible to said first switches, each of said first switches including a test switch having operating positions individually corresponding to the second switches forming any one of said groups, a by-pass selector switch corresponding to the second switches forming one of said groups, a tie switch associated with said by-pass selector switch and having operating positions individually corresponding to said first switches and to the second switches forming a particular one of said groups, means operative to seize one of said first switches and said selector switch, means responsive to the seizure of said selector switch for causing said tie switch to operate to the position corresponding to said one first switch, means responsive to the operation of said tie switch to said last-named position for causing the partial operation of said one first switch, means responsive to the partial operation of said one first switch for associating the second switches forming said particular group with the test switch of said one first switch, means responsive to the operation of said last-named test switch to said last-named position for causing said one first switch to complete its operation, thereby to seize said one second switch, and means responsive to the operation of said last-named means for causing said tie switch to operate to a position corresponding to said one second switch.
- 30 16. In a by-pass switching system, a plurality of first switches, a plurality of groups of second switches accessible to said first switches, each of said first switches including a test switch having operating positions individually corresponding to the second switches forming any one of said groups, a by-pass selector switch corresponding to the second switches forming one of said groups, a tie switch associated with said by-pass selector switch and having operating positions individually corresponding to said first switches and to the second switches forming a particular one of said groups, means operative to seize one of said first switches and said selector switch, means responsive to the seizure of said selector switch for causing said tie switch to operate to the position corresponding to said one first switch, means responsive to the operation of said tie switch to said last-named position for causing the partial operation of said one first switch, means responsive to the partial operation of said one first switch for associating the second switches forming said particular group with the test switch of said one first switch and for arresting the operation of said tie switch, means also responsive to the partial operation of said one first switch for causing said test switch to operate to a position corresponding to an idle one of said particular group of second switches, means responsive to the operation of said last-named test switch to said last-named position for arresting the operation of said last-named test switch and for causing said one first switch to complete its operation thereby to seize said one second switch, means responsive to the operation of said last-named means for again initiating the operation of said tie switch, and means operative when said tie switch is operated to the position corresponding to said one second switch for arresting the operation of said tie switch.
- 35 17. In a by-pass switching system, a plurality of first switches, a plurality of groups of second switches accessible to said first switches and individually having incoming trunk lines terminat-

- ing at said first switches, each of said trunk lines including a test conductor, each of said first switches including a test switch comprising a test wiper and test contacts arranged to have individually connected thereto the test conductors of the trunk lines individually extending to the second switches forming any one of said groups, a by-pass selector switch corresponding to the second switches forming one of said groups, a tie switch associated with said by-pass selector switch and having operating positions individually corresponding to said first switches and to the second switches forming a particular one of said groups, means operative to seize one of said first-named switches and said selector switch, means responsive to the seizure of said selector switch for causing said tie switch to operate to the position corresponding to said one first switch, means responsive to the operation of said tie switch to said last-named position for causing the partial operation of said one first switch, means responsive to the partial operation of said one first switch for connecting the test conductors of the trunk lines extending to the switches of said particular group to the test contacts of the test switch in said one first switch, means also responsive to the partial operation of said one first switch for initiating the operation of said last-named test switch, whereby the test wiper of said last-named test switch is caused successively to engage said test contacts, means operative when the test wiper of said last-named test switch engages a test contact corresponding to an idle one of the second switches of said particular group for arresting the operation of said last-named test switch and for causing said one first switch to complete its operation, thereby to seize said one second switch, means responsive to the operation of said last-named means for again initiating the operation of said tie switch, and means operative when said tie switch is operated to the position corresponding to said one second switch for arresting the operation of said tie switch.
18. In a by-pass switching system, a plurality of first switches, a plurality of second switches accessible to said first switches, a by-pass selector switch including a test relay, means operative to seize said by-pass selector switch, a tie switch associated with said selector switch and successively operative to a first position corresponding to a selected one of said first switches and to a second position corresponding to a selected one of said second switches in response to seizure of said selector switch, test circuits for said test relay, said test circuits being so connected and arranged that said test relay is operated from one of its two positions to the other each time said tie switch is operated to one of said two positions, and means controlled by said relay for causing the operation of said one first switch.
19. In a by-pass switching system, a plurality of first switches, a plurality of second switches accessible to said first switches, a by-pass selector switch including a test relay, means operative to seize said by-pass selector switch, a tie switch associated with said selector switch and successively operative to a first position corresponding to a selected one of said first switches and to a second position corresponding to a selected one of said second switches in response to seizure of said selector switch, test circuits for said test relay, said test circuits being so connected and arranged that said test relay is operated from one of its two positions to the other each time

said tie switch is operated to one of said two positions, means controlled by said relay for causing the operation of said one first switch, and means operative in response to the second operation of said test relay for arresting the operation of said tie switch.

20. In a by-pass switching system, a plurality of first switches, a plurality of second switches accessible to said first switches, a by-pass selector switch including a test relay, a tie switch associated with said by-pass selector switch and having operating positions individually corresponding to said first switches and to a group of said second switches, means operative to seize said selector switch and one of said first switches, means responsive to the seizure of said selector switch for initiating the operation of said tie switch, a test circuit for said test relay, said test circuit being so connected and arranged that said test relay operates from one of its two positions to the other when said tie switch is operated to the position corresponding to said one first switch, said one first switch being partially operative in response to the operation of said test relay to its said other position and said test relay being operative to its said one position in response to the partial operation of said one first switch, means responsive to the last-mentioned operation of said test relay to its said one position for selecting an idle one of said group of second switches, means operative when said one second switch is selected for causing said one first switch to complete its operation and for again initiating the operation of said tie switch, a second test circuit for said test relay, said second test circuit being so connected and arranged that said test relay operates from its one position to the other position when said tie switch is operated to the position corresponding to said one second switch, and means responsive to the last-mentioned operation of said test relay for arresting the operation of said tie switch.

21. In a by-pass switching system, a plurality of first switches, a plurality of second switches accessible to said first switches, a by-pass selector switch including a test relay, a tie switch associated with said by-pass selector switch and having operating positions individually corresponding to said first switches and to a group of said second switches, means operative to seize said selector switch and one of said first switches, means responsive to the seizure of said selector switch for initiating the operation of said tie switch, a test circuit for said test relay, said test circuit being so connected and arranged that said test relay is energized thereover and operates when said tie switch is operated to the position corresponding to said one first switch, means responsive to the operation of said test relay for arresting the operation of said tie switch, said one first switch being partially operative in response to the operation of said test relay, means responsive to the partial operation of said one first switch for interrupting said test circuit to deenergize said test relay, means responsive to the resulting restoration of said test relay for selecting an idle one of said group of second switches, means operative when said idle one of said second switches is selected for causing said one first switch to complete its operation and for again initiating the operation of said tie switch, a second test circuit for said test relay, said second test circuit being so connected and arranged that said test relay is energized and operates when said tie switch is operated to the position corresponding

to said one second switch, and means responsive to the second operation of said test relay for arresting the second operation of said tie switch.

22. In a telephone system, a plurality of lines divided into groups, a plurality of finder switches of the crossbar type having access to said lines, two sets of operating magnets included in each of said switches, the magnets of one set in each switch individually corresponding to said groups of lines and the magnets of the other set in each switch individually corresponding to the lines of each group, a by-pass selector switch, a tie switch associated with said by-pass selector switch and having operating positions individually corresponding to said finder switches, means responsive to the initiation of a call on one of said lines for seizing said selector switch, means responsive to the seizure of said selector switch for causing said tie switch to operate to a position corresponding to an idle one of said finder switches, means operative when said tie switch is operated to said last-named position for causing the operation of the magnet in said one finder switch which corresponds to the one group of lines including the calling line, means operative in response to the operation of said last-named means for selecting the calling line from said one group of lines, and means operative when the calling line is selected for causing the operation of the magnet in said one finder switch which corresponds to the calling line.

23. In a telephone system, a plurality of lines divided into groups, a plurality of finder switches of the crossbar type having access to said lines, two sets of operating magnets included in each of said switches, the magnets of one set in each switch individually corresponding to said groups of lines and the magnets of the other set in each switch individually corresponding to the lines of each group, each of said finder switches including a test switch having operating positions individually corresponding to the lines of each group, a by-pass selector switch, a tie switch associated with said by-pass selector switch and having operating positions individually corresponding to said finder switches, means responsive to the initiation of a call on one of said lines for seizing said selector switch, means responsive to the seizure of said selector switch for causing said tie switch to operate to a position corresponding to an idle one of said finder switches, means operative when said tie switch is operated to said last-named position for causing the operation of the magnet in said one finder switch which corresponds to the one group of lines including the calling line and for initiating the operation of the test switch in said one finder switch, means operative in response to the operation of said last-named magnet for marking the calling line in said last-named test switch, means operative to arrest the operation of said last-named test switch when said last-named test switch is operated to the position corresponding to the calling line, and means operative in response to the operation of said last-named means for causing the operation of the magnet in said one finder switch which corresponds to the calling line.

24. In a telephone system, a plurality of lines divided into groups, a plurality of finder switches of the crossbar type having access to said lines, two sets of operating magnets included in each of said switches, the magnets of one set in each switch individually corresponding to said groups of lines and the magnets of the other set in each switch individually corresponding to the lines of

each group, a plurality of by-pass selector switches, tie switches individually associated with said by-pass selector switches and each having operating positions individually corresponding to said finder switches, a distributor switch having access to said by-pass selector switches, means responsive to the initiation of a call on one of said lines for initiating the operation of said distributor switch, means operative to arrest the operation of said distributor switch when said distributor switch is operated to a position corresponding to an idle one of said selector switches, means responsive to the operation of said last-named means for causing the tie switch associated with said one selector switch to operate to a position corresponding to an idle one of said finder switches, means operative when said tie switch is operated to said last-named position for causing the operation of the magnet in said one finder switch which corresponds to the one group of lines including the calling line, means operative in response to the operation of said last-named means for selecting the calling line from said one group of lines and means operative when the calling line is selected for causing the operation of the magnet in said one finder switch which corresponds to the calling line.

25. In a telephone system, a plurality of lines divided into groups, a plurality of finder switches of the crossbar type having access to said lines, two sets of operating magnets included in each of said switches, the magnets of one set in each switch individually corresponding to said groups of lines and the magnets of the other set in each switch individually corresponding to the lines of each group, each of said finder switches including a test switch having operating positions individually corresponding to the lines of each group, a plurality of by-pass selector switches, tie switches individually associated with said by-pass selector switches and each having operating positions individually corresponding to said finder switches, a distributor switch having access to said by-pass selector switches, means responsive to the initiation of a call on one of said lines for initiating the operation of said distributor switch, means operative to arrest the operation of said distributor switch when said distributor switch is operated to a position corresponding to an idle one of said selector switches, means responsive to the operation of said last-named means for causing the tie switch associated with said one selector switch to operate to a position corresponding to an idle one of said finder switches, means operative when said tie switch is operated to said last-named position for causing the operation of the magnet in said one finder switch which corresponds to the one group of lines including the calling line and for initiating the operation of the test switch in said one finder switch, means operative in response to the operation of said last-named magnet for marking the calling line in said last-named test switch, means operative to arrest the operation of said last-named test switch when said last-named test switch is operated to the position corresponding to the calling line, and means operative in response to the operation of said last-named means for causing the operation of the magnet in said one finder switch which corresponds to the calling line.

26. In a telephone system, a plurality of lines divided into groups, a plurality of finder switches of the crossbar type having access to said lines, two sets of operating magnets included in each

- of said switches, the magnets of one set in each switch individually corresponding to said groups of lines and the magnets of the other set in each switch individually corresponding to the lines in each group, operating circuits for each of said magnets, a plurality of by-pass selector switches, tie switches individually associated with said by-pass selector switches and having operating positions individually corresponding to said 10 finder switches, a distributor switch having access to said by-pass selector switches, means responsive to the initiation of a call on one of said lines for initiating the operation of said distributor switch and for preparing the operating circuits 15 for the magnets corresponding to the group of lines including the calling line, means operative to arrest the operation of said distributor switch when said distributor switch is operated to a position corresponding to an idle one of said selector switches, means responsive to the operation of said last-named means for causing the tie switch associated with said one selector switch to operate to a position corresponding to an idle one of said 20 finder switches, thereby further to prepare the operating circuit for the magnet in said one finder switch which corresponds to the group of lines including the calling line, means operative to complete said last-mentioned circuit when said tie switch is operated to said last-mentioned position, means operative in response to the operation of said last-mentioned means for selecting the calling line from said one group of lines and for preparing the operating circuit for the magnet in said one finder switch which corresponds to the calling line, and means operative in response to the selection of said calling line for completing 25 said last-named circuit.
27. In a telephone system, a plurality of lines divided into groups, a plurality of finder switches of the crossbar type having access to said lines, 40 two sets of operating magnets included in each of said switches, the magnets of one set in each switch individually corresponding to said groups of lines and the magnets of the other set in each switch individually corresponding to the lines in each group, operating circuits for each of said magnets, each of said finder switches including a test switch having operating positions individually corresponding to the lines of each group, a plurality of by-pass selector switches, tie switches 45 individually associated with said by-pass selector switches and having operating positions individually corresponding to said finder switches, a distributor switch having access to said by-pass selector switches, means responsive to the initiation of a call on one of said lines for initiating the operation of said distributor switch and for preparing the operating circuits for the magnets corresponding to the group of lines including the calling line, means operative to arrest the operation of said distributor switch when said distributor switch is operated to a position corresponding to an idle one of said selector switches, means responsive to the operation of said last-named means for causing the tie switch associated with said one selector switch to operate to a position 50 corresponding to an idle one of said finder switches, thereby further to prepare the operating circuit for the magnet in said one finder switch which corresponds to the group of lines including the calling line, means operative to complete said last-mentioned circuit when said tie switch is operated to said last-mentioned position and for initiating the operation of the test switch in said one finder switch, means operative in response to 55
- 70
- 75

the operation of said last-named magnet for marking the calling line in said last-named test switch, means operative to arrest the operation of said last-named test switch when said last-named test switch is operated to the position corresponding to the calling line, said last-named test switch being operative to prepare the operating circuit for the magnet in said one finder switch which corresponds to the calling line when operated to the position corresponding to the calling line, and means responsive to the operation of said last-named means for completing said last-named operating circuit.

28. In a telephone system, a plurality of lines divided into groups, a main switch of the cross-bar type having access to said lines, said switch including two sets of operating magnets, the magnets of one set individually corresponding to said groups of lines and the magnets of the other set individually corresponding to the lines in each group, an impulse responsive by-pass selector switch operative to select one line included in one of said groups of lines, and means included in said by-pass selector switch for causing the operation of the magnets in said main switch which respectively correspond to said one group of lines and to said one line.

29. In a telephone system, a plurality of lines divided into groups, a main switch of the cross-bar type having access to said lines, said switch including two sets of operating magnets, the magnets of one set individually corresponding to said groups of lines and the magnets of the other set individually corresponding to the lines in each group, an impulse responsive by-pass selector switch operative to select a called line included in one of said groups of lines, a preceding by-pass selector switch operative to seize said first-named selector switch, line testing means in said preceding selector switch, means operative to cause said line testing means to test said called line following the operation of said first-named selector switch to select said called line, and means operative in response to the operation of said last-named means for causing the operation of the magnets in said main switch which respectively correspond to said one group of lines and to said called line.

30. In a telephone system, a plurality of lines divided into groups, a main switch of the cross-bar type having access to said lines, said switch including two sets of operating magnets, the magnets of one set individually corresponding to said groups of lines and the magnets of the other set individually corresponding to the lines in each group, an impulse responsive by-pass selector switch operative to select one line in one of said group of lines, a control switch included in said selector switch, means operative during the operation of said by-pass selector switch for marking in said control switch said one group of lines and said one line, and means including said control switch for causing the operation of the magnets in said main switch which respectively correspond to said one group of lines and to said one line.

31. In a telephone system, a plurality of lines divided into groups, a plurality of main switches of the crossbar type having access to said lines, each of said switches including two sets of operating magnets, the magnets of one set in each switch individually corresponding to said groups of lines and the magnets of the other set in each switch individually corresponding to the lines of each group, an impulse responsive by-pass selec- 70

75

tor switch operative to select one line in one of said groups of lines, a tie switch associated with said selector switch and having operating positions individually corresponding to said main switches, means operative to seize said selector switch, means responsive to the seizure of said selector switch for selecting one of said main switches and for causing said tie switch to operate to the position corresponding to said one main switch, a control switch associated with said selector switch, means operative during the operation of said selector switch for marking in said control switch said one group of lines and said one line, and means including said control switch for causing the operation of the magnets in said one main switch which respectively correspond to said one group of lines and to said one line.

32. In a telephone system, a plurality of lines divided into groups, a plurality of main switches of the crossbar type having access to said lines, each of said switches including two sets of operating magnets, the magnets of one set in each switch individually corresponding to said groups of lines and the magnets of the other set in each switch individually corresponding to the lines of each group, an impulse responsive by-pass selector switch operative to select one line in one of said groups of lines, a tie switch associated with said selector switch and having operating positions individually corresponding to said main switches, means operative to seize said selector switch, means responsive to the seizure of said selector switch for selecting one of said main switches and for causing said tie switch to operate to the position corresponding to said one main switch, a control switch associated with said selector switch, means operative during the operation of said selector switch for marking in said control switch said one group of lines and to said one line, said control switch being operative to cause the operation of the magnets in said one main switch which respectively correspond to said one group of lines and to said one line, and means operative to initiate the operation of said control switch only after said tie switch and said selector switch have completed their respective operations.

33. In a telephone system, a plurality of lines divided into groups, a plurality of main switches of the crossbar type having access to said lines, each of said switches including two sets of operating magnets, the magnets of one set in each switch individually corresponding to said groups of lines and the magnets of the other set in each switch individually corresponding to the lines of each group, an impulse responsive by-pass selector switch operative to select one line in one of said groups of lines, a tie switch associated with said selector switch and having operating positions individually corresponding to said main switches, means operative to seize said selector switch, means responsive to the seizure of said selector switch for selecting one of said main switches and for causing said tie switch to operate to the position corresponding to said one main switch, a control switch associated with said selector switch and including a first set of contacts individually corresponding to said groups of lines and a second set of contacts individually corresponding to the lines of each group, means operative during the operation of said selector switch for marking the contact corresponding to said one group of lines in said first contact set and for marking the contact corresponding to said one line in said second contact set, means including

a second control switch associated with said one main switch and arranged to be operated in synchronism with said first-named control switch for causing the operation of the magnets in said one main switch which respectively correspond to said marked contacts, and means operative to initiate the operation of said control switches only after said tie switch and said selector switch have completed their respective operations.

34. In a telephone system, a plurality of lines divided into groups, a plurality of main switches of the crossbar type having access to said lines, each of said switches including two sets of operating magnets, the magnets of one set in each switch individually corresponding to said groups of lines and the magnets of the other set in each switch individually corresponding to the lines of each group, an impulse responsive by-pass selector switch operative to select one line in one of said groups of lines, a relay operative following the operation of said selector switch to select said one line, a tie switch associated with said selector switch and having operating positions individually corresponding to said main switches, means operative to seize said selector switch, means responsive to the seizure of said selector switch for selecting one of said main switches and for causing said tie switch to operate to the position corresponding to said one main switch, a relay operative following the operation of said tie switch to the position corresponding to said one main switch, a control switch associated with said selector switch, means operative during the operation of said selector switch for marking in said control switch said one group of lines and said one line, said control switch being operative to cause the operation of the magnets in said one main switch which respectively correspond to said one group of lines and to said one line, and means jointly controlled by said relays for initiating the operation of said control switch.

35. In a telephone system, a plurality of lines divided into groups, a plurality of main switches of the crossbar type having access to said lines, each of said switches including two sets of operating magnets, the magnets of one set in each switch individually corresponding to said groups of lines and the magnets of the other set in each switch individually corresponding to the lines of each group, an impulse responsive by-pass selector switch operative to select a called line in one of said group of lines, a preceding by-pass selector switch operative to seize said first-named by-pass selector switch, line testing means in said preceding selector switch, a tie switch associated with said first-named selector switch and having operating positions individually corresponding to said main switches, means responsive to the seizure of said first-named selector switch for selecting one of said main switches and for causing said tie switch to operate to the position corresponding to said one main switch, a control switch associated with said first-named selector switch, means operative during the operation of said first-named selector switch for marking in said control switch said one group of lines and said called line, said control switch being operative to cause the operation of the magnets in said one main switch which respectively correspond to said one group of lines and to said called line, and means operative to initiate the operation of said control switch and said line testing means only after said tie switch and said first-named selector

switch have completed their respective operations.

36. In a telephone system, a first group of lines divided into a plurality of subgroups, a second group of lines also divided into subgroups, a plurality of first switches of the crossbar type, each of said switches including two sets of operating magnets, a plurality of groups of second switches, the second switches of different groups having access to different subgroups of said lines, the magnets of one set in each of said first switches individually corresponding to said groups of lines and the magnets of the other set in each of said first switches individually corresponding to said second switches, by-pass selector switches individually corresponding to said groups of lines, tie switches individually corresponding to said by-pass selector switches and having operating positions individually corresponding to said first and second switches, means operative to seize one of said first switches, an impulse responsive by-pass switch operative to seize one of said selector switches and to select one subgroup of said lines in response to a series of impulses transmitted thereto, means responsive to the seizure of said one by-pass selector switch for causing the associated tie switch to operate to a position corresponding to said one first switch, means responsive to the operation of said last-named tie switch to said last-named position for causing the operation of the magnet in said one first switch which corresponds to said one subgroup of lines, means operative in response to the operation of said last-named magnet for selecting an idle one of the group of second switches having access to said one subgroup of lines and for causing the operation of the magnet in said one first switch which corresponds to said one second switch, and means responsive to the operation of said last-named means for causing said last-named tie switch to operate to the position corresponding to said one second switch.

37. In a telephone system, a first group of lines divided into a plurality of subgroups, a second group of lines also divided into subgroups, a plurality of first switches of the crossbar type, each of said switches including two sets of operating magnets, a plurality of groups of second switches, the second switches of different groups having access to different subgroups of said lines, the magnets of one set in each of said first switches individually corresponding to said subgroups of lines and the magnets of the other set in each of said first switches individually corresponding to said second switches, by-pass selector switches individually corresponding to said groups of lines, tie switches individually corresponding to said by-pass selector switches and having operating positions individually corresponding to said first and second switches, means operative to seize one of said first switches, an impulse responsive by-pass switch operative to seize one of said selector switches and to select one subgroup of said lines in response to a series of impulses transmitted thereto, means responsive to the seizure of said by-pass one selector switch for causing the associated tie switch to operate to a position corresponding to said one first switch, means responsive to the operation of said last-named tie switch to said last-named position for causing the operation of the magnet in said one first switch which corresponds to said one subgroup of lines, means operative in response to the operation of said last-named

magnet for selecting an idle one of the group of second switches having access to said one subgroup of lines and for causing the operation of the magnet in said one first switch which corresponds to said one second switch, means responsive to the operation of said last-named means for causing said last-named tie switch to operate to the position corresponding to said one second switch, each of said second switches including two sets of operating magnets, the magnets of one set in each second switch individually corresponding to different smaller subgroups of one of said subgroups of lines and the magnets of the other set in each second switch individually corresponding to the lines of the smaller subgroups, said one selector switch being operative to select a called line in one of the smaller subgroups of lines accessible to said one second switch in response to two series of impulses transmitted thereto, and means operative only following the operation of said tie switch and the operation of said one selector switch for causing the operation of the magnets in said one second switch which respectively correspond to said one smaller subgroup of lines and to said called line.

38. In a telephone system, a first group of lines divided into a plurality of subgroups, a second group of lines also divided into subgroups, a plurality of first switches of the crossbar type, each of said switches including two sets of operating magnets, a plurality of groups of second switches, the second switches of different groups having access to different subgroups of said lines, the magnets of one set in each of said first switches individually corresponding to said subgroups of lines and the magnets of the other set in each of said first switches individually corresponding to said second switches, by-pass selector switches individually corresponding to said groups of lines, tie switches individually corresponding to said by-pass selector switches and having operating positions individually corresponding to said first and second switches, means operative to seize one of said first switches, an impulse responsive by-pass switch operative to seize one of said selector switches and to select one subgroup of said lines in response to a series of impulses transmitted thereto, means responsive to the seizure of said one by-pass selector switch for causing the associated tie switch to operate to a position corresponding to said one first switch, means responsive to the operation of said last-named tie switch to said last-named position for causing the operation of the magnet in said one first switch which corresponds to said one subgroup of lines, means operative in response to the operation of said last-named magnet for selecting an idle one of the group of second switches having access to said one subgroup of lines and for causing the operation of the magnet in said one first switch which corresponds to said one second switch, and means responsive to the operation of said last-named means for causing said last-named tie switch to operate to the position corresponding to said one second switch, line testing means in said impulse responsive by-pass switch, each of said second switches including two sets of operating magnets, the magnets of one set in each second switch individually corresponding to different smaller subgroups of one of said subgroups of lines and the magnets of the other set in each second switch individually corresponding to the lines of the smaller subgroups, said one selector

switch being operative to select a called line in one of the smaller subgroups of lines accessible to said one second switch in response to two series of impulses transmitted thereto, and means operative only following the operation of said tie switch and the operation of said one selector switch for causing said line testing means

to test the condition of said called line and for causing the operation of the magnets in said one second switch which respectively correspond to said one smaller subgroup of lines and to said called line.

JOHN WICKS.
